UNITED STATES PATENT OFFICE.

JOHN WICKS, OF OAK PARK, ILLINOIS, ASSIGNOR TO AUTOMATIC ELECTRIC INC., OF CHICAGO, ILLINOIS, A CORPORATION OF DELAWARE.

AUTOMATIC TELEPHONE SYSTEM.

Application filed June 17, 1920, Serial No. 389,633. Renewed January 2, 1926.

My invention relates in general to automatic telephone systems, but appertains more especially to such systems as include in addition to the regular local trunking system a second trunking system commonly known as a toll service trunking system, which is used for the interconnecting of toll or long distance lines with local lines; and the object of the invention is the provision 10 of circuit arrangements constituting essentially a third trunking system accessible to switches in both of the above systems and provided for the use of local subscribers and toll operators in calling automatic private 15 branch exchanges.

The use of an attendant's cabinet at each private branch exchange, with the inevitable complications, and the desirability of providing for absolutely uniform routine operations on the part of toll operators regardless of whether they are calling main exchange or private branch exchange lines, give rise to numerous problems of exceptional difficulty, which have been solved by 20 25 an entire redesign of the main to branch exchange trunk circuits. The new features introduced and their relation to the system as a whole will be fully explained hereinafter, reference being had to the accompanying 30 drawings.

The invention resides entirely in the branch exchange trunking system, and in Figs. 1, 2, 3, and 4 I have shown by means of the usual circuit diagrams all the apparatus in a trunking system of the above character which is required to complete a connection from the main exchange to a local line in a private branch exchange. Fig. 5 shows the wiring of the test contacts in a 35 40 branch exchange connector, and Fig. 6 is a schematic diagram illustrating the general layout of the system.

Referring to the latter figure, the schematic diagram, this is intended to show the 45 relation of the three trunking systems to each other and the manner in which they are blended together to form a complete telephone exchange system. The exchange may of course be of any desired capacity. However, for convenience it will be assumed to 50 have a capacity of 10,000 lines, that is, connections are established by means of first selectors, second selectors, and connectors of the usual Strowger vertical and rotary type. Thus the subscriber at substation A can ex- 55 tend a connection to the line of substation A² by means of the individual line switch C, the first selector D, the second selector F, and the connector H. This is the usual decimal trunking system and is used for completing local calls in the main exchange. 60

Toll connections are completed by means of a toll service trunking system, as before stated. For example, a toll operator can extend a connection to the line of substation A² by means of jack J, toll first selector D², toll transmission repeater E², toll second selector F², and the connector H. It will be noticed that the connector H is included in both trunking systems, and it appears then 70 that the local trunking system and the toll service trunking system are merged or blended together at the connectors. The connector H is known as a combination toll and regular connector, and it should be 75 stated that the layout as explained so far, including these combination connectors, is old and is fully described in my U. S. Patent #1,315,444, granted Sept. 2, 1919. The exact circuits used in the toll service trunking system, however, are preferably of the improved type shown in my copending application, Serial No. 379,217, filed May 6, 1920. 80

We now come to the private branch exchange trunking system, which is the subject matter of the invention. In order to handle calls to the branch exchanges a group of special second selectors, or selector repeaters, as they may be termed, is provided 90 which are accessible to local subscribers and also to toll operators by way of a certain designated level at the first selectors. In other words, the trunk lines from a certain level in the local first selectors and the trunk 95 lines from the corresponding level in the toll first selectors extend to the same group of second selectors, which are the special selectors referred to. This means that there are two trunk lines which extend to each 100 special selector and the trunk lines of each pair are merged or combined into one trunk line at a special switching mechanism or so called combination regular and toll transmission repeater which is interposed ahead 105 of the special selector to which the single trunk line thus formed is extended. The main to branch exchange trunk lines serving a branch exchange are accessible to the special second selectors and extend to the 110

branch exchange where after passing through the attendant operator's position or cabinet they terminate in connectors which have access to the local lines in the branch exchange.

With this explanation, a call may now be traced from the main exchange to the branch exchange. For example, the subscriber at substation A can extend a connection to the 10 line of branch substation A' by means of individual line switch C, first selector D, combination regular and toll transmission repeater E', special second selector F', and connector H'. Also a toll connection to the 15 same branch substation may be completed by way of jack J, toll first selector D², combination regular and toll transmission repeater E', special second selector F', and connector H'. It will be observed that the 20 route followed after the calls get past the first selectors is the same in both cases.

The circuit drawings show only apparatus which is included in the branch exchange trunking system, and which comprises the 25 combination regular and toll transmission repeater E', shown in Fig. 1, the special second selector F', Fig. 2, and a main to branch exchange trunk line which is accessible to the special selector F' and extends by way of 30 the attendant operator's cabinet, Fig. 3, to the connector H', Fig. 4. It should be mentioned that the trunk line shown is a two way trunk line, that is, it may be used not only for connections from the main exchange to the branch exchange, but also for 35 interchange connections which are originated in the branch exchange. This however, is more or less of an incidental feature and on that account is not indicated in the schematic drawing, Fig. 6, but is shown in the 40 circuit diagrams and will be explained in the detailed specification. To avoid confusion it may also be stated at this time that the combination regular and toll repeater E' is 45 not, strictly speaking, a repeater, at least not an impulse repeater, for it does not repeat impulses, this function being performed by the line relay of the adjacent selector F'. The location of this line relay is, however, a 50 mere matter of convenience and since the repeater E' performs all the other functions of a repeater of this type, and since it is, furthermore, conveniently known and referred to as such from its position in the 55 trunking system, it will be termed a repeater herein.

Main to branch exchange connection.

Having indicated in general terms the 60 purpose and scope of the invention, I will now describe in a more detailed manner the operation of the circuits when used for setting up a connection. For this purpose it will be assumed that a calling subscriber in 65 the main exchange, as for example, the sub-

scriber at substation A, Fig. 6, desires to obtain connection with a called subscriber at the branch exchange, as for example, the subscriber at substation A'. The general method of setting up the connection and the 70 apparatus involved have already been described briefly and the operation of the apparatus shown in the circuit drawings will now be pointed out in detail.

When the receiver is removed at substation A the individual line switch C is operated and the calling line is extended by means of the line switch to an idle first selector switch which we will assume to be the selector D, Fig. 6. The calling subscriber 75 will now operate his calling device in accordance with the first digit in the desired 80 number. Since the wanted party is in a private branch exchange the first digit in the number will correspond to the selector 85 level which is reserved for the branch exchange trunking system, and when the calling device is operated in accordance with this digit the selector D will be operated to raise its wipers to this level, after which the automatic trunk selecting movement is initiated as usual and the wipers are rotated automatically to select an idle trunk line. Referring now to Fig. 1, the trunk line comprising conductors 8, 9 and 10 is one of the 90 trunk lines to which the selector D has access by way of the branch exchange level and this trunk line extends from the multiple bank contacts 2, 3 and 4, located in the bank of the selector D and multiplied to 95 similar contacts in the banks of other selectors, to the combination regular and toll transmission repeater E'. Assuming now that the above trunk line is the one selected, 100 when the wipers of the selector D establish connection with the bank contacts 2, 3, and 4, the calling subscriber's line will be extended by way of the selector line wipers, bank contacts 2 and 4, conductors 8 and 10, upper 105 and lower left hand windings of the repeating coil R, conductors 70 and 71, normally closed contact springs of the reversing relay 18, conductors 72 and 73, normally closed 110 contacts of relay 24, conductors 62 and 63, and the upper and lower windings of the 115 double wound line relay 101 of the selector F', Fig. 2, to battery and ground respectively.

When the calling line is extended as above the line relay 101 is energized by current flow 120 through the calling substation and upon attracting its armature, closes a circuit for the slow acting release relay 102.

Upon energizing, relay 102 prepares the selector F' for operation in its vertical movement in the usual manner, and also places a ground upon the release trunk conductor 9. By this latter operation a ground potential is placed upon the test contact 3 and its 130 multiples in the banks of the selector

switches having access to the trunk line, and at the same time a holding circuit is established by way of the test wiper of the operated selector D, whereby this selector and the subscriber's individual line switch are maintained in operated position. Also, a connection may be traced from conductor 9 by way of the winding of relay 19 and conductor 12 to test contact 6. Relay 19 is of relatively low resistance and the test contact 6 and its multiples, which are located in the banks of the toll first selectors having access to the trunk line comprising conductors 11, 12, and 13, are brought near enough to ground potential by the above connection to make the trunk line busy. The grounding of conductor 9 also produces certain results in the repeater E' which are now to be pointed out. When this conductor is grounded current flows over a branch which extends from junction point 75 by way of the resistance 74 and the upper winding of the electropolarized relay 15 to battery. Resistance 74 is very high, preferably about 8000 ohms, and the relay 15 accordingly is not operated. Another branch circuit which may be traced extends from junction point 75 by way of armature 25 and its resting contact, conductor 76, and through the windings of relays 20 and 21 in parallel to battery, the circuit through the latter relay including the armature 48 of relay 22. Relays 20 and 21 are accordingly energized and produce various circuit changes which, however, are of no effect just at the present time. It may be noted, however, that relay 21 is the ring cut off relay and upon energizing, this relay disconnects the ringing equipment at the resting contacts of its armatures 43 and 46, and at the working contacts of these armatures extends the right hand windings of the repeating coil R through to the outgoing trunk conductors 60 and 64.

The calling subscriber may now operate his calling device in accordance with the next digit in the called number. As a result a series of interruptions is produced in the line circuit and the line relay 101 of the selector F' is deenergized a plurality of times, transmitting at each deenergization an impulse of current through the slow acting relay 103 and the vertical magnet 107 in series to battery. In response to these impulses the vertical magnet is operated to raise the wipers 130, 131, and 132 until they stand opposite the level of bank contacts which is assigned to the trunk lines extending to the particular branch exchange in which the wanted line is located. The slow acting relay 103 is energized in series with the vertical magnet and retains its armature in operated position throughout the vertical movement of the switch. At the first upward step of the shaft the off normal springs are shifted and relay 103 being now in operated position a circuit is completed from the grounded conductor 9 by way of the armature of relay 103, the off normal springs 114, and the winding of the stepping relay 104 to battery. Relay 104 is therefore energized, establishes a locking circuit for itself at its lower armature, and at its upper armature prepares a circuit for the rotary magnet 105. Upon the cessation of the impulses to the vertical magnet the slow acting relay 103 falls back and closes the circuit of the rotary magnet 105, which is energized and operates to rotate the switch wipers into engagement with the first set of contacts in the level opposite which they were raised. Near the end of its stroke the rotary magnet breaks the locking circuit of the stepping relay 104 which deenergizes and breaks the circuit of the rotary magnet. The rotary magnet then deenergizes also and again closes its interrupter contact. The operation now depends upon whether the trunk line terminating in the first set of bank contacts is busy or idle. If this trunk line is busy the test contact with which the test wiper 131 is in engagement will have a ground potential upon it and a circuit will be established which extends by way of the test wiper 131, armature 116 and its resting contact, the interrupter contact of the rotary magnet 105, off normal springs 114, and the winding of the stepping relay 104 to battery. By current flow over the above circuit the stepping relay 104 is again energized and again closes the circuit of the rotary magnet 105, which is therefore operated to advance the switch wipers into engagement with the next set of bank contacts. The circuit of the stepping relay 104 is of course broken as before, and this relay therefore deenergizes again, followed by the deenergization of the rotary magnet. This operation, in which the stepping relay and rotary magnet are energized alternately, will continue as long as the test wiper 131 engages busy or grounded test contacts. As soon as the wipers arrive at the first idle trunk line, however, which we will assume to be the trunk line shown in the drawing and comprising conductors 120 and 122, the test wiper 131 will find no ground potential on the test contact 134 associated with such trunk line, and as a result the stepping relay 104 will not again be energized. Instead, the switching relay 100, which has been short circuited heretofore, is operated by current flow from the grounded conductor 9 by way of the winding of said relay 100, the interrupter contact of the rotary magnet 105, off normal springs 114, and the winding of stepping relay 104 to battery. On account of the high resistance of said relay 100, relay 104 is not operated. Relay 100, upon energizing, connects the grounded conductor 9

to the test wiper 131 by means of its armature 116, thereby placing a ground potential upon the test contact 134 and its multiples in order to make the trunk line busy, and at the same time completing a circuit which extends by way of conductor 124, the winding of the switching relay 137, and the winding of the stepping magnet 138 of the line switch C² to battery. The line switch C² is a rotary line or trunk selecting switch used in extending the trunk line to a first selector in the main exchange in the establishment of branch to main exchange connections, and the energization of the switching relay 137, which is operated only about half way due to the fact that the line relay of the line switch is not operated, serves to disconnect the branch trunk conductors 123 and 125 from their normal battery and grounded connections in the line switch. The switching relay 100 of the selector F' also opens the vertical magnet circuit at its armature 117, the circuit being transferred to the release delaying relay 106, and at its armatures 115 and 118 extends the incoming trunk conductors 64 and 60 to the line wipers 130 and 132, it being noted that armatures 113 and 112 of relays 101 and 102, respectively, are in operated position. The calling main exchange subscriber has now established connection with the main to branch exchange trunk line comprising conductors 120 and 122, the connection having been established by means of the subscriber's individual line switch, a first selector in the main exchange, the combination regular and toll transmission repeater E', and the special second selector F'. Upon the completion of the connection to the trunk line a circuit is completed for the double wound line relay 205 of the connector H' which may be traced as follows: ground at G², lower winding of relay 205, resting contact of armature 239 and the said armature, contact springs controlled by armature 251, conductor 154, normally closed contacts of keys K¹ and K² at the attendant's cabinet, conductor 122, bank contact 135, wiper 132, working contact of armature 113 and the said armature, working contact of armature 118 and the said armature, conductor 60, armature 48 and its working contact, upper right hand winding of the repeating coil R, resistance 77, armature 27 and its resting contact, lower winding of the electropolarized relay 15, resistance 78, lower winding of the repeating coil R, working contact of armature 46 and the said armature, conductor 64, armature 115 and its working contact, armature 112 and its working contact, wiper 130, bank contact 133, conductor 120, normally closed contacts of keys K¹ and K², conductor 163, normally closed contacts controlled by armature 247, armature 235 and its resting contact, and the upper winding

of the line relay 205 to battery. It will be noted that the above circuit includes the lower winding of the electropolarized relay 15 at the repeater E'. The direction of current flow in the circuit is such that the windings of the electropolarized relay oppose each other at this time and the said relay is not operated. When the line relay 205 in the connector H' pulls up it closes a circuit for the slow acting release relay 204 at its armature 234. Upon energizing, relay 204 connects ground G³ to conductor 164 at armature 231, thereby lighting the busy lamp at the attendant's cabinet and also placing a ground potential upon the test contact 147 and its multiples in the banks of the automatic switches in the branch exchange which have access to the main exchange trunk lines. This renders the trunk line shown busy to these switches, and the lighting of the busy lamp of course indicates to the attendant operator that the trunk line is in use.

The apparatus is now in readiness for the operation of the connector H' in the branch exchange to complete the connection to the desired branch exchange line. When the calling subscriber operates his calling device in accordance with the next digit in the number a series of interruptions is produced in the circuit of the line relay 101 of the selector F' as before, but now since the switching relay 100 has been operated the line relay causes no further operation of the selector switch but instead it interrupts the circuit of the line relay 205 of the connector at its armature 113. The line relay 101 therefore operates as a repeating relay and repeats the interruptions produced in its own circuit into the circuit of the line relay 205, which latter relay is accordingly deenergized a plurality of times and at each deenergization transmits an impulse of current to the vertical magnet 214 over the following circuit: ground at G⁴, armature 234 and its resting contact, armature 232 and its working contact, armature 250 and its resting contact, off normal springs 281 and 283, winding of the vertical magnet 214 and the winding of the slow acting relay 207 to battery. This is the circuit over which the first impulse is transmitted. At the first upward movement of the shaft the off normal springs are shifted and the circuit is completed by way of off normal springs 281 and 282, armature 242 and its working contact (relay 207 being now in operated position), winding of the vertical magnet 214, and the winding of the slow acting relay 207 to battery. By the operation of the vertical magnet 214 the shaft of the connector H' is raised step by step until wipers 273-276, inclusive, stand opposite the level of bank contacts in which is terminated the desired line. The slow acting relay 207, which is energized in series

with the vertical magnet, maintains its armature attracted throughout the vertical operation of the switch. Upon energizing, relay 207 closes a circuit for the ring cut off relay 210 which may be traced as follows: grounded conductor 164, armature 229 of relay 203 and its resting contact, working contact of armature 240 and the said armature, tenth level switching springs 289 and 290, and the upper winding of the ring cut off relay 210 to battery. Upon energizing, relay 210 establishes a locking circuit for itself at its armature 255, and at its armatures 252 and 256 disconnects the ringing equipment and its own lower winding and closes the normally open contacts in the heavy talking conductors. Relay 210 also produces a number of other circuit changes, only one of which need be noticed now, which is the completion of a circuit for the slow acting relay 203 which extends as follows: grounded conductor 164, armature 254 of the relay 210 and its working contact, resting contact of armature 249 and the said armature, conductor 162, normally closed contacts of key K¹, Fig. 3, conductor 161, and the winding of the slow acting relay 203 to battery. Upon energizing, relay 203 produces various circuit changes which are of no effect just at present and which will be explained later on. When the transmission of impulses to the vertical magnet ceases the slow acting series relay 207 falls back and at its armature 242 transfers the operating circuit to the rotary magnet 215.

The calling subscriber may now operate his calling device in accordance with the final digit in the desired number, thereby producing another series of impulses in the circuit of the line relay 101 of the selector F', which are repeated as before into the circuit of the line relay 205 of the connector H'. The line relay 205 is accordingly again deenergized a plurality of times and transmits impulses to the rotary magnet 215 over the following path: ground at G⁴, armature 234 and its resting contact, armature 232 and its working contact, armature 250 and its resting contact, off normal springs 281 and 282, armature 242 and its resting contact, resting contact of armature 259 and the said armature, winding of the slow acting relay 212, resting contact of armature 271 and the said armature, and the winding of the rotary magnet 215 to battery. By the operation of the rotary magnet in response to the transmission of impulses over the above circuit the connector wipers 273-275, inclusive, are rotated the required amount and are finally brought to rest in engagement with the particular set of bank contacts in which is terminated the line of substation A', these bank contacts being the ones indicated in the drawing by the reference characters 277-280, inclusive. The relay 212 is energized in series with the rotary magnet, and being slow acting, remain in operated position throughout the rotary movement of the switch. At its armature 263 relay 212 connects the test wiper 274 to the test relay 211, and at its armature 265 closes a shunt around the back contact of armature 259 in order to guard against the possibility of the test relay being operated while the test wiper 274 is passing over busy test contacts.

When the test wiper 274 comes to rest in engagement with test contact 278, if the called line is busy the test wiper will find a ground potential upon the said test contact and the test relay 211 will be energized. The rotary movement having stopped, the slow acting series relay 212 is now deenergized and a locking circuit is established for the test relay 211 which extends from the grounded test contact 278 by way of test wiper 274, armature 258 and its working contact, normally closed contact springs controlled by armature 263 of relay 212, armature 269 and its resting contact, and the winding of the test-relay 211 to battery. In energized position relay 211 opens the rotary magnet circuit at its armature 259, opens the circuit of the switching relay 213 at its armature 260, and at its armature 262 connects a lead from the busy signalling machine Q to the lower heavy line conductor. As a result of the latter operation a busy signal is transmitted in the well known manner to the calling subscriber in the main exchange, who is thus advised that the desired line is engaged and is for the time being inaccessible. It may be mentioned that the tone from the busy signalling machine passes back over the lower heavy talking conductor to the repeating coil R at the repeater E', where it passes through the right hand windings of the repeating coil and returns by way of the upper heavy talking conductor, the condenser 292 at the connector H', working contact of armature 257 and the said armature, and the windings of relays 209 and 213 in parallel to battery. The return through the condenser 292 is in parallel with the branch which extends through the upper winding of the line relay 205 and is provided in order to increase the loudness of the busy signal.

The calling subscriber may now hang up his receiver, intending to release the switches and wait for the called line to become idle before he calls it again; or, if he so desires, he may wait on the line, the operation of the connector H' in connecting through and completing the connection being the same in either case. We will assume therefore that the calling subscriber does not hang up but waits until the busy condition is terminated. When the called line becomes disengaged, ground is removed from the test contact 278 and the test relay 211 will be deenergized.

- As a result a circuit is completed for the switching relay 213 which extends as follows: grounded conductor 164, resting contact of armature 260 and the said armature, lower winding of relay 213, resting contact of armature 263 and the said armature, test wiper 274, test contact 278, conductor 304, winding of the switching relay 301, and the winding of the stepping magnet 302 of the line switch C' to battery. Relays 213 and 301 are energized in series by the closure of the above circuit and the latter relay operates its armature sufficiently to disconnect the line conductors extending to substation A' from their normal battery and ground connections in the line switch. Owing to the fact that the line relay of the said line switch is not energized, relay 301 is not operated completely and the lines are not connected through to the line switch wipers. At connector H', when the switching relay 213 pulls up, it establishes a locking circuit for itself at its armature 268, opens the rotary magnet circuit at its armature 271, grounds the test wiper 274 at its armature 270, and at its armatures 266 and 272 closes the heavy talking conductors through to the line wipers 273 and 276.
- When the switching relay 213 locked itself at its armature 268 it also completed a circuit for relay 209 which is energized in parallel with the upper winding of the said relay 213. Relay 209 opens the operating circuit at its armature 250, prepares a circuit for relay 206 at its armature 248, prepares a circuit for relay 200 at its armature 299, and at its armature 249 breaks the circuit of the slow acting relay 203. The breaking of the latter circuit is of course followed by the deenergization of relay 203 but the explanation of the results produced by the falling back of this relay will be deferred for a moment in order to finish with the operations of relay 209. In addition to the circuit changes already mentioned this relay 209 reverses the heavy incoming line conductors 163 and 154 by means of its armatures 247 and 251. In order to make this a little more clear it may be explained that the line conductor 163, which before the operation of relay 209 extended through to the upper line wiper 273, is connected by way of the winding of low resistance series relay 202 and armature 251, and its working contact to the lower line wiper 276; while the lower line conductor 154, which before relay 209 is operated extends to the lower line wiper 276, is transferred by way of armature 247 and its working contact to the upper line wiper 273. When the line conductors 163 and 154 are reversed, as above explained, as regards their connection to the line wipers, they are also reversed as regards their connection to the upper and lower windings of the line relay 205, and it

follows that the direction of current flow in these conductors will be reversed. Consequently, the direction of current flow in the lower winding of the electropolarized relay 15, at repeater E', which relay is included in the line relay circuit, will be reversed also; and now, since the two windings of the said electropolarized relay assist each other, the relay will be operated. When the current flow in the trunk is reversed relay 15 first operates its armature 26, thereby short circuiting the high resistance 74, and the relay then pulls clear up by the complete energization of its upper winding. At its armature 27, relay 14 breaks the circuit through its own lower winding and at the working contact at this armature connects the upper trunk conductor by way of the battery feed relay 16 to battery. At the same time, at its armature 28, the lower line conductor is connected to ground. It should be observed that since the lines have been reversed at the connector H', relay 16 and the upper winding of the line relay 205 are both connected to the same side of the trunk and relay 16 accordingly is not energized at this time.

The operations at the repeater have not been completed, but further explanation thereof will be deferred while certain other operations which take place at the connector H' are explained. It was said before that when the relay 209 pulled up it broke the circuit of the slow acting relay 203. Upon deenergizing, relay 203 completes a circuit for the slow acting relay 206 as follows: grounded conductor 164, armature 229 and its resting contact, armature 248 and its working contact, and the winding of relay 206 to battery. Upon energizing, relay 206 establishes a locking circuit for itself at its armature 236, prepares a circuit for relay 208 at its armature 237, and at its armatures 235 and 239 disconnects the line relay 205. This latter operation leaves a clear talking circuit through the connector with no bridges across the line whatever. When the line relay 205 deenergizes, the slow acting release relay 204 would deenergize also and bring about the release of the connector were it not for special provisions which are introduced to prevent it. When the relay 206 pulls up, at the same time that the line relay is disconnected, relay 200 is connected to the lower line conductor as follows: conductor 154, working contact of armature 299 and the said armature, armature 238 and its working contact, resting contact of armature 224 and the said armature, upper and lower windings of relay 200 in series, and the resistance 294 to ground. Conductor 154 is the line conductor which at the repeater E' is connected with the battery feed relay 16, or with battery by way of resistance 80 if the ringing operation is taking place, and

- it follows that relay 200 will be energized by current from the repeater. Relay 200 is not fully operated, however, due to the fact that resistance 294, which should be of about 5000 ohms, is included in the circuit. It may be stated that the windings of relay 200 are of 500 and 1500 ohms resistance respectively, and the relay is so adjusted that the contact spring represented by the armature 222 is closed against ground at this time while the contact springs represented by armatures 220 and 221 are not operated. By the closure of the contact at armature 222 a holding circuit is completed for the slow acting release relay 204 which is thus maintained energized to prevent the release of the connection. The resistance of the circuit through relay 200 and the high resistance 294 is of course so great that the battery feed relay 16 at the repeater E' is not operated.
- Returning now to the repeater E', the explanation of the operations thereat which result from the energization of the electro-polarized relay 15 when the trunk conductors are reversed at the connector will be proceeded with. When relay 15 pulls up it breaks the circuit of relays 20 and 21 at its armature 25 and both of these relays deenergize. Relay 21 falls back first, and at its armature 44 completes a circuit for the relay 22 as follows: grounded conductor 9, armature 25 and its working contact, armature 44 and its resting contact, and the winding of relay 22 to battery. Upon energizing, relay 22 locks itself at its armature 47 and at its other armatures prepares a number of circuits which remain open at other relay contacts for the time being.
- When relay 21 deenergizes it also breaks the line conductors at its armatures 43 and 46 and at the resting contacts of these armatures closes the ringing circuit. Although the upper line conductor 60 is disconnected from the battery feed relay 16 by this operation, relay 200 at the connector H' does not deenergize, its circuit being closed by way of resistance 80 at armature 43. By the operation of the automatic ringing equipment shown immediately below the repeater E', Fig. 1, ringing current from the generator Gen is intermittently projected out over the called line to ring the bell at substation A'. The ringing circuit is substantially the same as the ringing circuits in common use and may be traced without difficulty from the generator by way of the upper winding of the ring cut off relay 21, conductor 64, conductor 120, conductor 163, and line conductor 305 (the lines having been reversed in the connector H' to substation A', where the circuit continues through the bridged ringer at the substation and returns by way of conductor 303, conductor 154, conductor 122, conductor 60, and through the resistance 80 to the ungrounded pole of the exchange battery. It is noted that the ringing circuit includes relay 202 at the connector H', but this relay is of relatively low resistance and moreover is shunted by a non-inductive resistance; accordingly, it does not respond to the ringing current. Attention is also called to the fact that there is a low capacity condenser bridged around the open contact in the lower line conductor at armature 46. This permits sufficient ringing current to leak back in the direction of the calling subscriber to give him the usual ringing current induction, so called, which indicates that the ringing operation is taking place.
- When the subscriber at substation A' removes his receiver from the hook to answer the call the ring cut off relay 21 at the repeater E' is operated in the usual and well known manner and upon attracting its armature 45 establishes a locking circuit for itself. Relay 21 also breaks the ringing circuit at the back contacts of its armatures 43 and 46, and at the working contacts of these same armatures closes the heavy talking conductors. The connection having been completed, the transmitter at substation A' is supplied with talking current through the right hand windings of the repeating coil R, the two resistances 77 and 78, and the winding of the battery feed relay 16. The battery feed relay 16 is therefore energized and at its armature 29 closes a circuit for the reversing relay 18 which, upon energizing, reverses the conductors 70 and 71 as regards their connection with outgoing trunk conductors 62 and 63 and also therefore as regards their connection with the windings of the double wound line relay 101 in the selector F', the lower winding of this relay, however, being short circuited by the ground connection at armature 32 of relay 17. This operation reverses the direction of current flow in the calling line and is the usual provision adopted for the purpose of operating a meter or coin collect device. Or in case the calling party is some operator, other than a toll operator, who is required to use the regular exchange trunking system for calling, this reversal of the current will give the calling operator supervision. It is noted in this connection that the information operators and trouble operators do not usually have access to the toll service trunking system but are required to use the regular local or subscriber's trunking system; and this is of course true also of the operators at private branch exchanges.
- At the connector H', when the called subscriber answers his telephone, the relay 202, which is in series with one side of the line, is energized and closes a circuit for relay 201. Upon energizing, relay 201 closes a circuit for the slow acting release relay 204 at its armature 225, and at its armature 224

- disconnects relay 200 from the line. This clears the talking circuit by removing the high resistance connection to ground through relay 200 which was used until now in order 5 to prevent the release of the connection. Relay 201 also closes a circuit for relay 208 at its armature 226 and this relay, upon energizing, establishes a locking circuit for itself at its armature 246. In addition, relay 10 208 prepares a circuit for the supervisory lamp at the attendant's cabinet by means of its armature 243.
- The complete connection has now been 15 established and the calling and called subscribers can converse as desired. The transmitter at the called station is supplied with talking battery through the winding of battery feed relay 16 at repeater E', as stated, while the transmitter at the calling substation 20 is of course supplied with talking battery through the upper winding of the line relay 101 in the selector F'. The circuit arrangements provide for hook supervision by the called subscriber, not only at the attendant's cabinet in the private branch exchange, but also at an operator's position in the main exchange, provided the calling party is an operator. The latter supervision is of course 25 controlled by the battery feed relay 16 at the repeater which controls the reversing relay 18. The supervisory lamp at the attendant's cabinet is controlled by the relay 202 at the connector. If the called subscriber should hang up his receiver relay 202 will fall back whereupon relay 201 will de-energize and now, since relay 208 is in operated position, a circuit for the supervisory lamp will be completed as follows: ground at G^a, armature 230 and its resting contact, armature 223 and its resting contact, armature 243 and its working contact, conductor 160, and the supervisory lamp at the attendant operator's position to battery. It is noted that whenever relay 201 is deenergized relay 200 is again connected from the lower side of the line to ground in order to hold up release relay 204 and prevent the release of the connector. If the calling subscriber should replace his receiver the connection is released by the deenergization of the line relay 101 at the selector F'. The release of the connector H' under these circumstances will no doubt be readily understood, and at any rate, it need not be explained in detail now because the release of this switch will be explained fully later on; it is noted, however, that when armature 113 of the line relay 101 is retracted it breaks the lower line conductor extending to the connector and causes relays 200 and 204 to fall back, the latter relay then closing the circuit of the release magnet 216. The release circuit at the selector F', however, is somewhat different from the usual release circuit and may be explained now to good 30 advantage. When the line relay 101 falls back it closes a circuit for the slow acting relay 106, which, upon energizing, grounds the release trunk conductor 9 and also opens the circuit of the release magnet 108. It follows that when the slow acting release relay 102 falls back an instant later, ground is not removed from conductor 9 and the release magnet circuit is not closed. Relay 102, however, opens the circuit of the slow 35 acting relay 106 and when this relay de-energizes ground is removed from conductor 9 and the release magnet circuit is closed. Relay 106 therefore operates to delay the release of the selector F' and the switches in 40 the main exchange. This delaying operation is of no particular consequence in connection with the circuits herein illustrated but is necessary under certain conditions and with certain types of equipment in order 45 to insure that the connector switch at the branch exchange be restored to normal position before the switching relay of the line switch associated with the trunk line at the main exchange is permitted to deenergize. 50 It is noted that as long as conductor 9 is grounded and the selector F' is held in operated position the switching relay 137 of the line switch C² will be maintained energized. 55
- 95
- Transferred connection.*
- As is explained in the preceding paragraph, if the calling subscriber hangs up his receiver the connection will be released; but 60 it will be convenient, in order to proceed with the explanation, to assume that the calling subscriber desires to obtain connection with some other line in the branch exchange, in which case he will not hang up 65 his receiver. It happens quite frequently, as is well understood, that the particular person wanted at a private branch exchange telephone may be temporarily absent in some other department, or it may be found after 70 the called subscriber has answered that the matters under consideration can best be dealt with by some other person. In either case it is desirable to have the attendant at the branch exchange transfer the connection 75 and thus relieve the calling subscriber of the trouble involved in disconnecting and calling the entire number over again. In such case the party first called will flash the operator by working his receiver hook in the 80 well known manner. This operation causes the relay 202 at the connector to deenergize intermittently and interrupt the circuit of relay 201. Each time the latter relay falls back it closes a circuit for the supervisory lamp at the attendant operator's position 85 over a path previously traced. It should be remembered that whenever relay 201 de-energizes it also connects relay 200 to one 90 side of the line and this relay of course al- 95

ways closes the contact at its armature 222 in order to maintain the release relay 204 energized.

When the attendant operator sees the supervisory lamp flashing she will answer by throwing her key K^1 to listening position. This bridges the operator's head set across the heavy talking conductors of the trunk and the operator is able to converse with either or both of the subscribers and find out what is wanted. Assuming now that the calling subscriber desires to have the call transferred to some other station in the branch exchange, as soon as this information is imparted to the operator the called party at substation A' will replace his receiver. Relays 202 and 201 now fall back, and since the key K^1 at the operator's position is in listening position, the latter relay connects the lower winding of relay 200 in bridge of the line over the following path: from the lower trunk conductor 154 by way of armature 238 and its working contact, resting contact of armature 224 and the said armature, lower winding of relay 200, conductor 156, and contacts of key K^1 to the upper trunk conductor 163. This relay is connected across the line in order to maintain the same closed should the operator afterwards restore her key, as will appear hereinafter. Relay 200 is energized by current from the battery feed relay at the repeater E' and is completely operated, closing a locking circuit for itself at its armature 220 which is independent of the contacts at the key. At its armature 221 relay 200 also connects ground to conductor 160 and thereby lights the supervisory lamp at the operator's position.

Having ascertained the number that the calling party desires to be transferred to, the attendant operator will throw her key K^1 to the "call in" position. By the operation of the key the heavy talking conductors of the trunk extending through the operator's position are broken, resistance 170 is connected in bridge of the section of the trunk which extends in the direction of the calling subscriber, and the operator's head set including the calling device S is connected in bridge of the section extending to the connector H'. When the trunk line is opened the section extending toward the connector is of course cleared from all battery connections and relay 200 is deenergized, followed by the deenergization of the slow acting release relay 204. The deenergization of the latter relay closes the circuit of the release magnet 216 and the connector H' is restored to normal in the usual and well known manner. Relay 204 also disconnects ground G³ from the conductor 164 and as a result all the relays in the connector which were locked up to this conductor are deenergized. This includes relays 206, 208, 209,

210 and 213. When the slow acting relay 206 falls back the line relay 205 is again connected in bridge of the trunk conductors 163 and 154, and since the operator's set is bridged across the trunk at the attendant's cabinet, the line relay is energized. The slow acting release relay 204 then pulls up also, again grounds conductor 164, and prepares the connector for the vertical operation thereof. In addition to relays 205 and 204, relay 203 is also energized at this time, its circuit being closed over conductor 161 at the key K^1 .

The operator may now operate her calling device in accordance with the digits in the local number of the desired line. When the dial is operated in accordance with the first digit in the number the circuit of the line relay 205 is interrupted a plurality of times and this relay transmits a series of impulses to the vertical magnet 214 over circuits previously traced. By the operation of the vertical magnet the wipers 273-276, inclusive, are raised step by step and are brought to rest opposite the desired level of bank contacts. The slow acting relay 207 is energized in series with the vertical magnet as before explained and with the same results, except that in the present case, since relay 203 is in operated position, relay 207 does not close the circuit of the ring cut off relay 210 and this latter relay remains deenergized. When the operator calls the next and final digit in the number the line relay 205 sends a series of impulses to the rotary magnet 215, which operates to rotate the wipers 273-276, inclusive, into engagement with the particular set of bank contacts in which the desired line is terminated. During the rotary movement of the switch the slow acting relay 212 is of course energized in series with the rotary magnet and connects the test wiper 274 with the test relay 211 in order that when the called line is finally found it may be tested in the manner already explained. This operation having been gone over already, it will be assumed that the called line is found to be idle, in which case, when the slow acting relay 212 deenergizes, the switching relay 213 will pull up in series with the switching relay of the line switch which is associated with the connected called line. These operations have all been described and may be passed over without further consideration. It should be recalled, however, that when the switching relay 213 energizes it establishes a locking circuit for itself at its armature 268, thereby also closing a circuit through the reversing relay 209. Upon energizing, relay 209 does not open the circuit of relay 203 as before, because conductor 161 is now grounded at key K^1 . In the present case, then, relay 209 simply reverses the trunk conductors 163 and 154 at the connector. By this operation relay 202 is in-

cluded in the circuit of the line relay 205 and is energized, thereby closing the circuit of relay 201 which energizes also.

The call has now been extended to a second line in the private branch exchange and since the ring cut off relay 210 has been left deenergized, ringing current will be projected over the called line from the connector switch. In this connection it may be stated that conductor 295 is a lead coming from a signalling machine similar to the one shown in Fig. 1. Having completed her work in setting up the connection, the attendant operator may now either wait on the line to make sure that the right party is obtained, or she may restore her key at once and leave the calling subscriber to control the connection. We will suppose first that she waits on the line until the called party answers. When the receiver is removed from the hook at the called station the ring cut off relay 210 is operated, establishes a locking circuit for itself at its armature 255, opens the ringing circuit at the back contacts of its armatures 252 and 256, and at the working contacts of these armatures completes the talking circuit. Relay 206 has not yet pulled up and the trunk conductors are open at the operator's position, and it follows therefore that the transmitter at the called station will be supplied with talking battery through the windings of the line relay 205 which is still in bridge of the line at the connector. The operator will now talk with the called party and if everything is O. K. she will restore the key K^1 to normal. This operation removes all bridges at her position and connects the line through as it was originally. In addition, the restoration of key K^1 breaks the circuit of relay 203 which upon deenergizing closes the circuit of the slow acting relay 206. Upon energizing, relay 206 disconnects the line relay 205 from the line and the called station is supplied with talking battery from the repeater E' . Relay 202 holds up in series with the line circuit and relay 201 is therefore held energized also to maintain the release relay 204 energized in order to prevent the release of the connector. The circuit conditions are now the same as in the case where the calling subscriber established the connection himself, in the first place.

In order to explain the operations fully it will now be assumed that after the operator has extended the connection to the second called line she restores her key K^1 at once, without waiting for the called party to answer. On restoring the key, the lines are cut through and relay 203 is deenergized as explained. When relay 203 falls back it closes the circuit of relay 206 which energizes and cuts off the line relay 205. At the same time, relay 206 connects relay 200 to the lower line conductor by means of its

armature 238, and relay 200 is energized by battery from the repeater E' . As before explained, this relay operates only enough to close the contact at its armature 222 in order to hold up the slow acting release relay 204. It will be noticed that when a call is transferred the ringing current is necessarily applied to the second called line from the connector H' , rather than from the repeater E' , as is the case when the connection is established by the main exchange subscriber himself. Since the attendant operator is involved in the establishment of the transferred connection, it is desirable that she be given supervision, and it will be observed now that since the ring cut off relay 210 is deenergized, the ringing operation being now going on, the supervisory lamp is lighted over the following circuit: grounded conductor 164, working contact of armature 268 and the said armature, armature 257 and its resting contact, armature 253 and its resting contact, resting contact of armature 228 and the said armature, conductor 160, and the supervisory lamp to battery. While the ringing operation is taking place the calling subscriber (or the attendant, if she is on the line) is given the usual ringing current induction by means of the path which extends from the line wiper 273 by way of the condensers 293 and 292 to the upper line conductor just back of the open contacts at the ring cut off relay 210. When the called party answers, the ring cut off relay 210 pulls up, locks itself as before, disconnects the ringing equipment, and closes the talking circuit. Relay 210 also opens the circuit of the supervisory lamp at its armature 254, and the lamp is extinguished to notify the attendant operator that the called party has answered.

The release of the connection is under the control of the calling subscriber and when he replaces his receiver all the automatic switches will be restored to normal as previously explained. It is understood, of course, that in case the called party does not answer, as indicated by the continuation of the lighted condition of the supervisory lamp, the operator may come in on the line again, and if necessary, can release the connector as before by throwing her call in key. The connector can then be reoperated to establish connection with some other line.

The foregoing describes the operations which take place in transferring a call to another local line, it being assumed that the second called line is idle. As stated heretofore, if the line to which the call is transferred is busy the operations incident to this condition of the called line are the same, so far as the operation of the test relay and the transmission of the busy signal to the calling party is concerned, as in the case previously described where the calling subscriber

established the connection himself. There are, however, certain operations having to do with the release of the connector H' by the attendant operator when a transfer has been attempted and the line found busy, which have not yet been touched upon and which will now be explained. It will be assumed that a call has been completed to a line in the branch exchange by a subscriber in the main exchange, that the attendant operator has been called upon to transfer the call, and that the line to which it is attempted to transfer the call is busy. Under these circumstances the connector will not cut through onto the called line, and the test relay 211 will energize to give the operator a busy signal. At this time the line and release relays 204 and 205 will be in energized position, as is also relay 203, but all the other relays, including relays 209 and 213, are at normal.

Having received the busy signal, the operator may now restore her key K¹ to normal. This disconnects the operator's head set and calling device and connects the trunk line through as it was originally. Relay 203 is also deenergized by the restoration of the key, but relay 206 does not pull up at this time, because its circuit is opened at armature 248 of relay 209. For the same reason, that is, because relay 209 is in normal position, it will be clear that the incoming line conductors have not yet been reversed at the connector and it follows that the main and branch exchange batteries will be connected in series over the trunk line. To make this a little more clear it may be explained that the battery feed relay 16 at the repeater E' and the lower winding of the line relay 205 at the repeater E' and the upper winding of the line relay 205. It follows that relays 16 and 205 are energized in series, the energization of the latter relay being of course effective to maintain the connector H' in operated position. The calling subscriber can now hear the busy signal which notifies him that the line to which it has been attempted to transfer his call is busy. The operator can leave the circuits in this condition if she so desires, and if the called line becomes idle the connector will cut through and the connection will be completed as in ordinary cases. Or if the calling subscriber hangs up his receiver, the entire connection will be released. Both these situations have been gone over before. On the other hand, if the operator considers it necessary or desirable to assist the calling subscriber further she may come in on the line and talk to him by throwing the key K² to "call out" position. This operation opens the trunk line at the attendant's position and thus cuts off the busy signal coming from the connector H' so that the parties can talk together without interference. It should be mentioned also, that the opening of the line by the "call out" key does not cause the release of the connector H' due to the fact that a circuit is completed for the lower winding of the relay 205 by way of resistance 149, which is connected to the lower trunk line conductor at the lower contacts of the key. Suppose now that the attendant desires to release the connector from the busy line and try some other number. It will be plain that she cannot do this by merely throwing the key K¹ to "call in" position as this would simply bridge her head set and calling device across the trunk line and the line relay 205 would stay energized. Special means is therefore necessary to accomplish the release under the conditions now existing, and to meet the requirements the release key is provided. When the key K² is thrown to the release position the two conductors of the trunk line are opened and as a result the line relay 205 and the slow acting release relay 204 are deenergized and the connector is released. At the same time a circuit is completed by way of conductor 159 and the tenth level switching springs 289 and 290 for the ring cut-off relay 210 which upon energizing closes the circuit of relay 203 over conductors 162 and 161. Upon energizing, relay 203 extends conductor 157, which is now grounded at the release key, to relays 209 and 213 which are accordingly energized also. Relay 209 performs its usual function of reversing the line and also breaks the circuit of relay 203, which falls back an instant later and closes the circuit of relay 206. Upon energizing, the latter relay disconnects the line relay 205 and connects relay 200 to the lower side of the line. The release key may now be restored to normal, in fact, it need only be operated momentarily, and the trunk line conductors are again connected through, ground being disconnected from conductors 159 and 157 at the same time. Relay 200 now pulls up from battery at the repeater and closes a circuit for the slow acting release relay 204 which accordingly energizes and connects the ground to conductor 164. As a result of the latter operation relays 206, 209, 210 and 213, all of which it will be noticed are slow acting, are locked up and remain in energized position. Although the shaft and wipers of the connector are now in normal position, it will be observed that the circuits of the connector so far as the relays are concerned are in the condition of having completed a connection with a called line which has not answered. In short, the connector is in the ordinary ringing position and if the attendant should not come back on the line no particular harm is done because the circuits are in condition to maintain disconnect supervision.

at any operator's cord circuit who may be calling and the connection can not become tied up. This condition will be considered more fully later on.

- 5 According to the previous assumption, however, the call is to be retransferred and the attendant operator may now proceed to call another number in the branch exchange by throwing the key K¹ to the "call in" position. By this operation the trunk line conductors are opened and her head set and calling device are bridged across the conductors extending toward connector H'. The opening of the trunk line causes relay 200 to deenergize, and the release relay 204 is therefore deenergized also to remove ground from conductor 164. All the various relays in the connector which have been locked up are now deenergized also, and relay 206 again connects the line relay 205 across the conductors of the trunk line. The operator's head set and calling device being in bridge of the trunk line the line and release relays 205 and 204 are now energized again and the connector is all ready to be reoperated. The operations which take place when the attendant operator sets up a local connection by use of her "call in" key have already been explained in detail.

30 *Rotary operation of connector.*

- In the foregoing pages I have explained how a connection is extended from a line in the main exchange to the line of substation A' in the branch exchange, the latter being a private or individual line. The connector H', however, is what is known as a rotary connector, and may have access to a number of groups of lines or trunk lines as well as to individual lines like the one shown in the drawing. For example, if the private branch exchange is located in a manufacturing establishment a certain department may have a plurality of lines extending thereto, all of which are reached by calling the same telephone number, the number called being the number of the first line in the group. An arrangement of this kind is common and well known in the art. In order to take care of the rotary feature the connector H' is provided with an additional test wiper which is the wiper 275, and also with an additional bank of test contacts which are associated with the said test wiper. In Fig. 5, I have shown all the test contacts in a certain level, and the way in which they may be connected in order to take care of the grouping of lines. The upper row of contacts are the regular test contacts which are engaged by the test wiper 274, while the lower row of contacts are the extra test contacts which are engaged by the special test wiper 275. If it is desired to combine certain lines into a group, the two test contacts associated with each of the lines ex-

cept the last are connected together. The test contacts associated with the last line of each group are left disconnected, as are also the test contacts which are associated with the individual lines. Thus, in Fig. 5, 70 with the test contacts connected as shown, the first four lines in the level constitute a group; the next three lines are individual lines; and the last three lines constitute a second group. 75

The operation of the connector H' as a rotary connector will now be briefly explained. It will be assumed that a call is initiated by the subscriber at the main exchange, and that the connector H' at the 80 branch is used to complete the connection, all as previously explained, except that in the present case the called number is the number assigned to a group of lines rather than to an individual line at the branch exchange. When the connection is completed to the first line of the group, if the line is busy there will be a ground potential upon the test contact with which the test wiper 274 is in engagement, and the test relay 211 will 90 be energized. Relay 211, upon energizing, establishes a locking circuit for itself and performs other circuit changes which have already been explained. Since the regular test contact and the special test contact 95 which are associated with each line in the group except the last are tied together, the test contact which is engaged by the special test wiper 275 will also have a ground potential upon it, and a circuit is therefore 100 established for relays 208 and 207 as follows: from the grounded test contact, by way of test wiper 275, resting contact of armature 264, interrupter contact of the 105 rotary magnet 215, armature 261 and its working contact, lower winding of relay 208 and the winding of the slow acting relay 207 to battery. Relays 207 and 208 are energized by current flow in the above circuit and the latter relay, upon energizing, 110 establishes a locking circuit for itself and relay 207 at its armature 244 in an obvious manner, and at its armature 245 closes a circuit for the rotary magnet 215 as follows: grounded conductor 164, armature 236 and 115 its resting contact, armature 245 and its working contact, resting contact of armature 271 and the said armature, and the winding of the rotary magnet 215 to battery. The 120 rotary magnet is accordingly energized and operates to rotate the wipers of the connector into engagement with the next set of contacts in the group. Near the end of its stroke the rotary magnet breaks the locking circuit of relay 208 at its interrupter contact. Relay 208 at once deenergizes and breaks the circuit of the rotary magnet which then 125 deenergizes also. The operation now depends upon whether the line associated with the second set of contacts in the group is 130

busy or not. If the line is busy there will be a ground potential upon both contacts as before, and relay 208 will again be energized, with the result that the rotary magnet is again operated to advance the wipers into engagement with the next set of test contacts. As soon as an idle line is reached neither test wiper will find a ground potential, the rotation of the switch will stop, the test relay 211 will deenergize and the switching relay 213 will be energized as previously explained to complete the connection. If all the lines in the group are busy the rotation of the switch will continue until the last line of the group is reached, whereupon, since the two test contacts associated with the last line are not connected together, the special test wiper 275 will find no ground potential and the rotation will stop. Test wiper 274, however, is still resting on a grounded test contact, for the last line in the group is busy, and the test relay 211 will remain energized. The circuit through relays 208 and 207 being now permanently broken, the slow acting relay 207, which maintains its armatures in operated position during the rotation of the switch, now energizes and at its armature 241 closes the lead to the busy signalling machine. It will be understood that relay 207 is included in the circuit of relay 208 for the sole purpose of maintaining this busy signalling circuit open while the switch is rotating, it being necessary to do this because the test relay 211 is energized before the rotation starts and it is not desired to give the calling party a busy signal unless all the lines in the group are busy.

Toll to branch exchange connection.

Having described the operations involved in establishing a connection from a local subscriber in the main exchange to a subscriber in the branch exchange, it will be convenient now to explain what takes place when a toll operator calls a subscriber in the branch exchange, with a view to pointing out wherein the operations differ from the operations already described. We may assume that the toll operator in front of whom the jack J, Fig. 6 appears has received a long distance call from some distant point which is directed to the subscriber at substation A' in the branch exchange. As previously explained, the present system provides for uniform routine operations on the part of the toll operator regardless of whether she is calling main exchange or branch exchange subscribers, and it will be understood therefore that the toll operator is not required to perform any unusual acts when calling a branch exchange subscriber or to discriminate in any way between subscribers in the main and branch exchanges. As a matter of fact, it is not necessary for the toll operator to know whether the party called for is located in the main exchange or in a branch exchange. To complete the required connection, then, the operator will simply take an idle one of her cord circuits and will plug it into the jack of an idle outgoing toll service trunk. The circuits of the toll service trunking system are preferably similar to those shown in my copending application previously referred to, and it may be stated at this point that the toll first selectors are substantially the same as the first selectors which are used in the local trunking system; in particular, it may be mentioned that the toll selectors are of the type which are controlled over the two sides of the line in series rather than over a separate conductor. Assuming then that the toll service trunk which terminates in the jack J, Fig. 6, is the trunk to be used, when the operator plugs into the jack the line relay of the toll first selector will pull up over the two sides of the trunk line in series and the slow acting release relay of the selector will be energized in the usual manner to prepare the switch for operation. The operator will now throw her calling device key whereby her head set and calling device is bridged across the two strands of the cord circuit in use. The circuits are now in readiness for the calling of the required number. When the calling device is operated in accordance with the first digit a series of interruptions is produced in the circuit of the line relay of the selector D², and the said selector is accordingly operated in the usual manner to raise its shaft step by step until the wipers stand opposite the level which is assigned to the branch exchange trunking system. At the end of the vertical movement of the selector the usual trunk selecting movement is initiated and the wipers of the selector are rotated automatically until they arrive at the contact set associated with an idle trunk line. Assuming that the trunk line comprising conductors 11, 12, and 13, which extends to the combination regular and toll transmission repeater E', Fig. 1, is the first idle trunk line, the wipers of the toll selector will be brought to rest in engagement with bank contacts 5, 6, and 7; and it follows that when the switching relay of the toll selector operates the line conductors of the toll service trunk will be extended by way of the line wipers of the toll selector, bank contacts 5 and 7, and conductors 11 and 13 to the left hand windings of the repeating coil R, whence they may be traced in the manner previously explained through the repeater E' to the line relay 101 of the selector F'. When the trunk is extended into connection with the repeater E' as just explained, the line relay 101 of the selector F' is energized over the two sides of the trunk line in series and closes a circuit for the slow act-

ing release relay 102. Upon energizing, relay 102 prepares the selector for operation in its vertical movement, and also places a ground upon the release trunk conductor 9. 5 By the latter operation a ground potential is placed upon test contact 3 and its multiples in the banks of the local first selectors having access to the repeater E', whereby the said repeater is made busy. At the same 10 time, a ground potential is placed on test contact 6 and its multiples in the banks of the toll first selectors which have access to the repeater. This renders the repeater E' busy to all toll selectors except the selector 15 in use; and as to the operated selector, the test wiper of such selector is now in engagement with the test contact 6 and a holding circuit is completed in the usual manner for maintaining the switch in operated position. 20 The foregoing operations are substantially the same as the ones described in the case where the call was extended by the local subscriber in the main exchange, except that now the repeater E' has been seized by a toll selector having access to the trunk line comprising conductors 11, 12 and 13, whereas in the former case the repeater was seized by a local first selector having access to the trunk line comprising conductors 8, 9, and 10. It 25 will be observed now, that the holding circuit for the toll first selector includes the relay 19 at the repeater, and this relay accordingly energizes in series with the switching relay of the toll first selector. At its armature 39 relay 19 prepares a circuit for relay 22, and at its armature 40 closes a circuit for relay 17. Upon energizing, relay 17 30 breaks the short circuiting connections normally existing around the resistances 81 and 82 by means of its armatures 31 and 35, respectively, and at its armature 32 breaks the ground connection which is provided for short circuiting the lower winding of the line relay 101 when the reversing relay 18 35 is operated on local connections. Relay 17 also prepares a circuit for the ring down alternating current relay 23 at its armature 30 and prepares other circuits at its armatures 33 and 34 which will be mentioned 40 hereinafter. Relays 19 and 17 are relays which operate only on toll connections and it will be understood that these relays are provided in order to suitably alter the circuits of the repeater to enable it to perform 45 the functions of a toll transmission repeater when handling this class of connections. In addition to the foregoing operations a flow of current is established in the polarizing winding of the electropolarized relay 15, and at the same time relays 20 and 21 are 50 energized with the usual results.

The toll operator may now operate her calling device in accordance with the remaining digits in the number, whereupon 55 the selector F' and the connector H' are op-

erated precisely as in the case previously explained to complete the connection to the line of substation A'. In order to fully explain the operations it will be assumed now that the line of substation A' is busy when 70 called. Under these circumstances the busy test relay 211 at the connector H' will be energized and locked up by way of the test wiper of the connector, and a busy signal will be transmitted in the usual manner back 75 to the calling toll operator. When the operator hears the busy signal she may of course withdraw the plug and release the connection, but ordinarily she will find it more convenient to simply restore her calling device key and wait until the called line becomes idle. When the key is restored the supervisory relay at the operator's cord circuit is bridged across the two strands of the cord in place of the operator's head set and 80 calling device and thus maintains the circuit of the line relay 101 closed and prevents the release of the connection. It should be stated at this time that the supervisory relay is preferably a polarized relay and is so 85 connected that it is not operated at this time. It follows that the supervisory lamp at the operator's cord circuit will not be lighted.

When the called line becomes idle the test relay 211 is deenergized and the switching relay 213 is energized to complete the connection at the connector, all as previously explained. When the switching relay 213 is energized it establishes a locking circuit for itself and at the same time closes a circuit for the reversing relay 209. Upon energizing, relay 209 reverses the trunk conductors 163 and 154, incoming to the connector H', and thereby reverses the direction of current flow in the lower winding of the 100 electropolarized relay 15 at the repeater E'. The latter relay is accordingly operated, locks itself to the grounded conductor 9 at its armature 26, cuts out its own lower winding at the back contact of its armature 27, and at the working contacts of armatures 27 and 28 connects the inner terminals of the right hand repeating coil windings by way of resistances 77 and 78 to the battery feed relay 16 and to ground, respectively. Relay 110 15 also breaks the circuit of relays 20 and 21 at the back contact of its armature 25; but now, due to a special circuit arrangement, relay 21 is not permitted to deenergize. Since relay 19 is in operated position, when 115 relay 15 pulls up a circuit is closed for relay 22 at the working contact of armature 25, and upon energizing, said relay 22 closes a locking circuit for relay 21 at its armature 48. Relay 21 is slightly slow acting and this 120 locking circuit is closed before it has time to deenergize, the circuit extending to ground at armature 40 when it is first established and then, upon the deenergization of slow 125 acting relay 20, being transferred to the 130

grounded conductor 9 by way of armature 51 of relay 23. An additional result of the energization of relay 22 is the closure of a circuit for the reversing relay 18 at armature 49. Upon energizing, relay 18 reverses the direction of current flow in the conductors of the calling line the same as it did in the connection previously described, except that in the present case, since relay 17 is in operated position, the lower winding of the line relay 101 is not short circuited, and the resistances 81 and 82 are connected in series in the two sides of the line circuit, respectively. These resistances, it may be mentioned, are used merely to prevent an unnecessarily heavy flow of current over the toll service trunk.

When the current is reversed in the conductors of the trunk line the polarized supervisory relay which is in bridge of the line at the operator's cord circuit is operated and lights the supervisory lamp. The lighting of the lamp advises the operator that the called line has become idle and that the connection has been completed. The next operation is to ring the called subscriber. It will be observed that in a case where the toll operator is calling, the automatic ringing does not start immediately upon the completion of the connection but may, however, be started at any time thereafter by the operator. To accomplish this the operator simply has to actuate her ringing key momentarily whereby ringing current is projected out over the trunk line and actuates the alternating current relay 23 at the repeater E', said relay being now connected around the condenser which connects the two left hand windings of the repeating coil R. Relay 23 is accordingly operated and at the back contact of its armature 51 breaks the locking circuit of the ring cut off relay 21. At the same time relay 23 connects ground to conductor 62 in order to insure that line relay 101 will not be caused to de-energize, or chatter its armature, by the ringing current, as might otherwise sometimes occur. When the locking circuit of the ring cut-off relay 21 is broken this relay falls back and closes the usual ringing circuit. The called station is now signalled automatically in the usual manner. When the called party answers and removes his receiver from the hook the ring cut off relay 21 pulls up again and reestablishes its locking circuit at its armature 45, the operator having by this time restored her ringing key and relay 23 being in normal position. The talking circuit having been completed, relay 16 is energized by flow of current over the called line and upon attracting its armature 29 closes a circuit for relay 24. Upon energizing, relay 24 disconnects conductors 72 and 73 from conductors 62 and 63, respectively, and connects the resistance 83 in bridge of the two latter conductors, thereby completing a local energizing circuit for the line relay 101 of the selector F'. Conductors 72 and 73 are now entirely disconnected from any current source and it follows that the flow of current over the trunk line coming from the operator's position will entirely cease. As a result, the supervisory relay at the operator's cord circuit is deenergized and the supervisory lamp is extinguished. By this means the operator is notified that the called subscriber has answered his telephone, and she may now cut in on the line with her listening key and talk to the called party in order to ascertain whether or not he is the party actually wanted, or for any other necessary purpose. When all is ready the required toll connection may be completed by inserting the other end of the cord circuit in use in the jack associated with the toll line over which the call has been received and the subscribers may converse as desired.

Attention is called to the fact that when a toll connection is established as described in the foregoing paragraphs the release of the connection is taken away from the control of the toll operator and is controlled by the called party after he has answered. This is accomplished by the relay 24 which closes a local circuit for the line relay 101 of the selector F', and at the same time cuts said line relay off from the trunk line which comes from the operator's position. This arrangement of the circuits permits the operator to withdraw the plug from the jack in order to change cord circuits without releasing the connection. And in addition, because of the absence of current flow on the trunk, it produces a quiet and efficient talking circuit. Although all the relay operations which take place at the connector H' during the establishment of the foregoing connection have not been gone over in detail, these operations will be readily understood because of the explanation which was given in the case where the connection was established by a local subscriber in the main exchange; and it may be stated at this time that the circuit operations which take place at the connector H' are the same in all cases regardless of whether the connector is being used in a toll connection or in a local connection. The differentiation between toll and local calls is done at repeater E'.

Calling attendant at branch exchange.

The process of establishing main to branch exchange connections by local main exchange subscribers and by the toll operators having been explained, it remains now to explain the establishment of certain other classes of connections which may be considered as variations of the above, and which introduce certain operating features at the attendant's

cabinet. Inasmuch as all of the equipment in the branch exchange operates substantially the same no matter whether the calling party is a toll operator or a local subscriber in the main exchange, the various connections which will now be considered will be gone over only once, it being assumed that the calling party is a toll operator; and where any difference exists, or special operations are required, mention will be made thereof in the course of the explanation.

The first connection of this kind which will be explained is where the toll operator calls the attendant at the branch exchange.

It will be understood that although most of the subscribers at the branch exchange may be called directly, their numbers being listed in the general directory, it is impossible to secure all desired connections in this way, as there are always a certain percentage of calls to a private branch exchange which must be directed to the attendant operator and then routed by her to the proper local stations. As a matter of fact, the principal reason for providing an attendant is to have some one who is familiar with the local departments ready to answer calls then necessary, route the calls to the proper stations, and exercise general supervision over the incoming traffic. In order to provide for calling the attendant operator the tenth level of the incoming connectors is reserved, and the circuits are so arranged that when a connector is raised to this level its further operation is prevented and a ring down relay at the attendant's position is connected in bridge of the trunk in use in readiness to be operated by ringing current which is automatically transmitted over the trunk line, the automatic ringing operation being started immediately when the calling party is a local subscriber in the main exchange or later on at the option of the operator when the calling party is the toll operator. The circuits will best be understood from a detailed consideration of the operations which take place and this will now be proceeded with. In its preliminary stages the connection is established precisely as has been already described, a toll first selector being operated to establish connection with the repeater E', after which the special second selector F' is operated to extend the connection to the connector H'. The next digit to be called is the digit 0 and when the calling device is operated in accordance with this digit the connector H' is operated under control of the line relay 205 to raise its shaft step by step until the wipers stand opposite the tenth level. On the first vertical step the circuit of the ring cut off relay 210 is closed by the slow acting relay 207, which operates in series with the vertical magnet, and upon energizing relay 210 establishes a locking circuit for itself and also closes a circuit for

the slow acting relay 203, all as previously explained. When the shaft is raised to the tenth level, the tenth level switching springs are shifted and spring 290 is disengaged from spring 289 and is brought into engagement with spring 291. When this occurs a circuit is completed for relays 213 and 209 as follows: grounded conductor 164, armature 255 and its working contact, springs 290 and 291, resting contact of armature 257 and the said armature, and windings of relays 209 and 213 in parallel to battery. Relays 213 and 209 are accordingly energized and the latter relay reverses the heavy line conductors at the connector and also opens the circuit of relay 203, which deenergizes and closes the circuit of relay 206. Upon energizing, relay 206 cuts off the line relay 205. Before this occurs, however, due to the reversal of the line conductors by relay 209, the electropolarized relay 15 at the repeater E' is operated with the result that relays 22 and 18 are energized and relay 20 is deenergized, the deenergization of relay 21 being prevented as previously explained by the establishment of a new locking circuit when relay 22 pulls up.

Returning to the connector H', the line relay 205 has been disconnected, as stated, and relay 200 is connected to the lower line conductor in order to hold up the slow acting release relay 204 and prevent the release of the connection. With the switch in this condition the ring down relay 150 at the operator's position is bridged across the trunk line as follows: from upper trunk conductor 163 by way of the upper winding of relay 150, conductor 153, and rotary off normal springs 296 to the upper line wiper 273 which, since relays 213, 210, and 209 are energized, is connected to the lower trunk conductor 154 by way of armature 266 and its working contact, armature 252 and its working contact, and the working contact of armature 247 and the said armature. The toll operator may now throw her ringing key with the result that ringing current is projected over the trunk line to operate the alternating current relay 23 at the repeater E'. This breaks the locking circuit of the ring cut off relay 21, which accordingly deenergizes and closes the ringing circuit. The ring down relay 150 which is in bridge of the trunk at the branch exchange is now operated, locks itself at its lower armature, and at its upper armature closes a circuit for the call signal or answering lamp at the attendant's position.

When the attendant perceives the lighted lamp she will respond by throwing her key K¹ to listening position. By this operation the locking circuit of relay 150 is broken and the said relay deenergizes and extinguishes the answering lamp. In addition, when the listening key is operated the lower winding

- of relay 200 is connected across the trunk as explained heretofore. This has the same effect as the removal of the receiver by a called subscriber, and the ring cut off relay 5 at the repeater E' is operated, closes a locking circuit for itself, cuts off the ringing current, and closes the talking conductors. The lower winding of relay 200 being across the line at the connector, relay 16 is now 10 energized and closes a circuit for relay 24 which pulls up, closes a local circuit for the line relay 101 of the selector F' and disconnects the said relay from the trunk line incoming from the toll operator's position. 15 The latter operation causes the supervisory relay in the toll operator's cord circuit to deenergize and extinguish the supervisory lamp. If the toll operator has left the line, she is thus advised that the attendant at the 20 branch exchange has answered and she will then come in on the line and the two operators can converse together as desired.
- In order to extend the connection to the proper local station the attendant operator 25 will throw her key K¹ to the "call in" position. This operation opens the trunk line at the attendant operator's position, connects resistance 170 in bridge of the section of trunk extending in the direction of the 30 toll operator, thereby keeping the supervisory circuits in answered condition, and connects the attendant operator's head set and calling device S in bridge of the section which extends to the connector H'. When the trunk line is opened the relay 200, which has been maintained energized by battery from the repeater in order to prevent the release of the connector switch, is deenergized, and an instant later the slow acting 35 release relay 204 falls back and the connector is released and restored to normal through the medium of release magnet 216. From this point on, the connection is established the same as in the case where the attendant operator transferred a call which 40 was completed initially by a local main exchange subscriber and was later transferred at the instance of one of the parties to a second called line in the branch exchange. 45 In view of the detailed explanation of this operation which has already been given it will be unnecessary to go over it again.

Blocked calls.

- 55 In the ordinary operation of the system connections are established as has been set forth in the preceding pages, that is, a main exchange subscriber or a toll operator can call the branch subscribers directly or if 60 desired they can call the attendant and have her extend the connections to the appropriate local stations. This method of operating is of course necessary at night or at any time when the attendant is liable to be absent from the switchboard temporarily, or 65 busy with other matter, it being essential at such times that the circuits be in such condition that through connections can be established from the main exchange without the assistance of the attendant operator. At 70 other times, however, it may be desirable to have the attendant receive all calls which are directed to the branch exchange regardless of whether the calling party is calling the attendant or a local station, the calls 75 being extended to the desired local station by the attendant operator as fast as they are received. In order to provide for handling the connections in this manner a so-called blocking key is provided for each trunk line 80 passing through the attendant operator's position, the blocking key associated with the trunk line shown in the drawing being the key K³ in Fig. 3. If this key is left in operated position any call which is received 85 at the trunk line will be directed to the operator, and the manner in which this is accomplished will now be pointed out.
- For this purpose it will be assumed that a toll operator is calling a local subscriber 90 in the branch exchange over the trunk line shown in the drawings, the key K³ at the attendant operator's position being in operated position. When the connection is extended to the connector H' by the operation 95 of the selector F', the line relay 205 at the connector is energized, followed by the energization of slow acting release relay 204, all the operations up to this point being the same as have been described in the previous 100 cases. Upon energizing, relay 204 produces the usual circuit changes and in addition closes an energizing circuit for the slow acting relay 203 as follows: ground at G⁴, off normal springs 97, armature 233 and its working contact, conductor 155, conductor 152, contact springs of key K³, conductor 151, resting contact of armature 249 and the said armature, conductor 162, normally closed contacts of key K¹, conductor 161, and the winding of relay 203 to battery. Relay 203 is energized over the above circuit and at its armature 227 closes a circuit for 105 relays 209 and 213 as follows: grounded conductor 155, normally closed contacts of key K¹, conductor 158, contacts of key K³, conductor 157, armature 227 and its working contact, resting contact of armature 257 and the said armature, and windings of relays 209 and 213 in parallel to battery. Relays 209 and 213 are therefore energized, and from this point on the operations are the same as in the case where the call was originally directed to the attendant by calling 110 the digit 0. Although these operations 115 have already been explained it may perhaps be of advantage to go over them again briefly. When relay 209 energizes it breaks the circuit of relay 203 which thereupon de- 120 energizes and closes the circuit of relay 206. 130

Upon energizing, relay 206 connects relay 200 to the lower line conductor and at the same time cuts off the line relay 205. Before this occurs, however, relay 209 has reversed the trunk conductors at the connector and the electropolarized relay 15 at the repeater E' is operated with the usual results, including the energization of relays 22 and 18, the deenergization of slow acting relay 20, and the closure of a locking circuit for maintaining the ring cut off relay 21 in energized position. Now when the toll operator rings out on the trunk line to signal the called party the alternating current relay 23 at the repeater E' is operated as before to open the locking circuit of the ring cut off relay 21. Upon deenergizing, relay 21 closes the ringing circuit and the ring down relay 150 at the attendant's position is operated, closing a locking circuit for itself and lighting the answering lamp at the attendant operator's position. The attendant responds by throwing her key K¹ to listening position, which bridges the relay 200 across the trunk line and stops the ringing by energizing the ring cut off relay 21 at the repeater E'. Relay 21 having pulled up and locked, the battery feed relay 16 energizes in series with relay 200, which is across the line at the connector, and closes the circuit of relay 24 which energizes and extinguishes the supervisory lamp at the toll operator's cord circuit in the manner before explained. The toll operator may now come in on the line, and upon finding that the attendant at the branch exchange has answered the call, will inform her of the desired number. The connection is then extended to the proper local station by the attendant at the branch exchange.

Branch to main exchange connection.

This finishes what is considered to be a reasonably complete explanation of the operation of the trunk circuits in completing the various main to branch exchange connections which are possible in the system, and I will now proceed to a brief explanation of the operations which occur when connections are extended in the opposite direction. It is understood that the private branch exchange herein contemplated is what is known as a hundred line system, local connections being established through the medium of the subscriber's individual line switches and local connector switches, to which the former ordinarily have direct access. In order that the branch subscribers may also have access to the main exchange, trunk lines for the purpose of connecting with subscribers in the main exchange, however, the conventional trunking arrangement is modified by the interposition of so called selector repeaters between the line switches and connectors. These selector re-

peaters may have access to the local connectors through one level, the first, for example; they may have access also to information trunks extending to the attendant's position from another level; and, finally, they may have access to the trunk lines which connect the main and branch exchanges. The tenth level is usually reserved for the latter trunk lines. Thus in Fig. 3 the conductors 143, 144, and 145, which may be considered as a branch of the main to branch exchange trunk line comprising conductors 120 and 122, extend to bank contacts 146, 147, and 148, respectively, which are multiplied in the tenth level of these selector repeaters. This branch trunk line then, being accessible to the selector repeaters in the branch exchange, constitutes the means by which the branch exchange subscribers are given access to the main exchange. Although a number of suitable selector repeater circuits which may be used are well known, reference is made to the U. S. Patent to Jacobsen, No. 1,332,217, March 2, 1920, which shows a suitable circuit for this purpose.

In order to extend the trunk line comprising conductors 120 and 122 into connection with an idle first selector when the same is used for branch to main exchange connections, the branch trunk line comprising conductors 123, 124, and 125 is provided which extends to the individual line switch C², Fig. 2. The line switch C² is of the well known rotary type in which the wipers have no normal position and move in a forward direction only, and is operable automatically when a call is received over the trunk line to extend the same into connection with a trunk line extending to an idle first selector switch. One of these latter trunk lines is indicated in the drawing and comprises conductors 126, 127, and 128, which are accessible to the wipers of the line switch C² and extend to a local first selector in the main exchange.

Having described the general arrangement in use, it will now be assumed that a calling branch subscriber desires to extend a connection to a subscriber in the main exchange, and the operations which take place at the trunk circuit will be briefly pointed out. The calling subscriber, after removing his receiver and obtaining connection with an idle selector repeater, will operate his calling device in accordance with the digit 0, thereby raising the wipers of the selector repeater to the tenth level. The automatic trunk selecting movement is then initiated, and the wipers of the switch are rotated automatically in search of an idle trunk line. Assuming that the trunk line comprising conductors 143, 144, and 145 is the first one found to be idle, the wipers will be brought to rest in engagement with bank contacts 146, 147, and 148, or similar contacts connected in multiple.

therewith, and the line wipers will be extended by way of conductors 143 and 145, conductors 120 and 122, and conductors 123 and 125 to the line switch C^2 at the main exchange. The connection having been established a ground potential is placed upon the test wiper of the selector repeater in use, and a circuit is completed for relay 206 in the connector H' as follows: from the grounded test wiper by way of test contact 147, conductor 144, conductor 164, armature 231 and its resting contact, and the winding of relay 206 to battery. Relay 206 is accordingly energized and clears the trunk line by disconnecting the line relay 205 from in bridge thereof. It is noted that relay 200 is not connected at this time due to the fact that relay 209 is in normal position. Returning now to the selector repeater, when connection is established with bank contacts 146, 147, and 148, a bridge is closed across the line wipers of the switch and as a result the line relay 139 of the line switch C^2 is energized. By the operation of the line relay a circuit is closed for the switching relay 137 in series with the stepping magnet 138, and at the same time the test wiper 141 is connected to the junction of the said relay and stepping magnet. This latter operation is to provide for advancing the switch wipers in case they should happen to be in engagement with a busy trunk line. We may assume, however, that the trunk line shown in the drawing is idle, and it follows therefore that no rotation of the switch will take place and switching relay 137 will at once energize to extend the conductors 123 and 125 by way of wipers 140 and 142, the bank contacts engaged thereby, and conductors 126 and 128 to the line relay of the first selector switch in which these conductors terminate. The line and release relays of the first selector are accordingly energized in the usual manner and the latter relay places ground upon conductor 127 to complete a holding circuit which extends by way of the said conductor 127, test wiper 141, winding of the switching relay 137, and the winding of the stepping magnet 138 to battery. A branch of the above circuit extends by way of conductor 124 to test contact 134 and its multiples in the banks of the special second selector switches, such as the selector F' , whereby the main to branch exchange trunk line is made busy.

The calling subscriber may now operate his calling device in accordance with the digits in the number of the desired station in the main exchange. The resulting interruptions or impulses are repeated by the selector repeater in the branch exchange, and a series of switches in the main exchange, including a plurality of selectors and a final connector switch, are operated to complete the connection in the usual and well under-

stood manner. The called subscriber is signalled from the connector in the main exchange as usual and when he responds the two connected subscribers can converse as desired. The connection is released when the branch exchange subscriber hangs up his receiver. This opens the line circuit and the selector repeater restores to normal in the usual manner and breaks connection with the main exchange trunk line, whereupon the switches in the main exchange will be restored also.

Branch to main exchange connection, established by attendant.

If they so desire, the branch exchange subscribers may avail themselves of the services of the attendant operator in securing main exchange connections. In obtaining a connection in this manner a calling branch exchange subscriber will remove his receiver and will then call the digit which corresponds to the level in which the local information trunks are terminated, thereby operating the selector repeater with which he has been connected to establish connection with an idle one of these information trunks. When the attendant operator answers the branch exchange subscriber will give her his own number and also the number of the main exchange subscriber with whom he desires to be connected, after which he will hang up his receiver and wait until he is called back by the operator. Having received the order and made note thereof if necessary, the attendant operator will proceed to establish the connection in the following manner: Assuming that the trunk line shown in the drawing is idle and is taken for use, the key K^2 is thrown to "call out" position, by which operation the operator's head set and calling device S are bridged across the two conductors 120 and 122 of the trunk line extending to the main exchange. At the same time, these conductors are opened in the direction of the connector H' in the branch exchange and a ground potential is placed upon conductor 164. By the latter operation the busy lamp associated with the trunk line is lighted, relay 206 in the connector H' is energized to cut off the line relay 205, and a ground potential is extended by way of conductor 144 to test contact 147 and its multiples in the banks of the selector repeaters of the branch exchange in order to make the trunk line busy.

When the operator's head set and calling device are connected in bridge of the trunk line the line switch C^2 at the main exchange is operated in the manner previously explained to extend the connection to an idle first selector switch. The operator may now operate her calling device in accordance with the digits in the number of the

main exchange subscriber with whom connection is wanted, and as a result the selector with which connection has been established, a second selector switch, and a connector switch are successively operated to complete the connection. The bell at the called station is now rung automatically in the usual manner. When the called subscriber answers the operator will ask him 10 to wait a moment and will then proceed to call the branch exchange subscriber back in order to complete the desired connection.

To call the branch exchange subscriber the operator will of course throw the key 15 K^1 to "call in" position. When the key is operated the trunk conductors are opened, resistance 170 is connected across the section extending toward the main exchange in order to prevent the release of the main 20 exchange switches after the key K^2 has been restored, and the operator's head set and calling device are bridged across the trunk conductors which extend to the connector H' . Key K^2 may now be restored to normal and as a result ground is disconnected 25 from conductor 164, thereby deenergizing relay 206. The line relay 205 is therefore connected in bridge of the incoming line conductors at the connector and is energized 30 in series with the calling device S at the attendant operator's position. Upon energizing, relay 205 closes the circuit of relay 204 which accordingly is energized also and again connects ground to conductor 164.

The operator may now operate her calling device in accordance with the number of the branch exchange subscriber who initiated the call. The operations which take 35 place are precisely the same as in the case where the operator is transferring an incoming call, hence will not be again described in detail. When the connection is completed the operator may wait for the party in the branch exchange to answer, or 40 she may restore her key at once. Assuming now that the key is restored immediately, relay 203, which has been held energized over conductor 161, falls back and closes the circuit of relay 206. The connector is 45 not released, however, due to the main exchange connection which has been established. The connectors in the main exchange are provided with the usual back bridge reversing relays and since the called 50 party in the main exchange has answered, the conductors of the trunk line incoming to the connector in use will have been reversed, and the lower side of the trunk line shown will now be the side which extends 55 to the ungrounded pole of the main exchange battery. It follows that relay 200, which was connected to the lower side of the line at the connector H' by the energization of relay 206, is energized by current 60 from the connector at the main exchange

and operates to close the circuit of the slow acting release relay 204 as usual, the connector being thereby prevented from releasing. When the subscriber in the branch exchange answers he is supplied with talking 70 battery from the line relay of the connector in the main exchange. Relays 202 and 201 of course are energized, the former being in series with one conductor of the talking circuit, and relay 200 is disconnected. Relay 201 grounds the release relay 204 to hold up the connector H' during conversation. The operations which take place in case the operator waits for the branch exchange subscriber to answer will be readily understood 80 in view of previous explanations. Relay 205 is of course left across the line to furnish talking battery to the branch exchange subscriber when he answers, and is disconnected when the key K^1 is restored to normal by 85 the deenergization of relay 203 and the resulting energization of relay 206.

The complete talking connection having been established conversation may now proceed as desired. Although the release of the connection will probably be understood without difficulty, it will be explained briefly in order to avoid any chance of confusion. Suppose the main exchange subscriber hangs up his receiver first; the conductors incoming to the main exchange connector are thereupon reversed to normal condition by the deenergization of the back bridge relay of such connector, but since the branch exchange subscriber still has his receiver off, the line relay of the main exchange connector will be held up and the connection will not be released. Suppose now that the branch exchange subscriber hangs up. As a result relay 202 at connector H' and the 100 line relay of the main exchange connector are both deenergized. The deenergization of the line relay at the main exchange connector permits the release of the main exchange switches in the usual and well understood manner. At the connector H' the deenergization of relay 200 is followed by the deenergization of relay 201, and now since the lower conductor of the trunk line goes to the grounded pole of the battery at the main exchange instead of to the ungrounded pole, relay 200 at the connector H' will not again be energized and the slow acting release relay 204 will fall back to bring about 105 the release of the connector H' . Thus all the switches in use are restored to normal. In the case where the subscriber at the branch exchange hangs up his receiver first, the release of the connection will of course take place immediately, for the deenergization of the line relay at the main exchange connector will of course cause the main exchange switches to release, and since the lower conductor of the trunk line normally goes 110 to ground at the line switch C^2 in the main 115 exchange, the connector H' will be released. The deenergization of the line relay at the main exchange connector will cause the main exchange switches to release, and since the lower conductor of the trunk line normally goes to ground at the line switch C^2 in the main 120 exchange, the connector H' will be released. The deenergization of the line relay at the main exchange connector will cause the main exchange switches to release, and since the lower conductor of the trunk line normally goes to ground at the line switch C^2 in the main 125 exchange, the connector H' will be released. The deenergization of the line relay at the main exchange connector will cause the main exchange switches to release, and since the lower conductor of the trunk line normally goes to ground at the line switch C^2 in the main 130 exchange, the connector H' will be released.

exchange, relay 200 at the connector H' will not operate to interfere with the release of the connector H'.

It has been assumed in the foregoing that the attendant operator sets up the connection by first calling the subscriber in the main exchange and then calling the subscriber in the branch exchange. If desired these operations may be reversed and the branch exchange subscriber may be called back first, in fact, in some cases it will be convenient and proper to do this. There is nothing especially novel in setting up the connection in this way beyond what has already been explained and it is believed that the operations will be readily understood without any further discussion thereof. It may be pointed out, however, that after the connection at the branch exchange has been established, and after the "call out" key has been operated by the attendant in order to call the main exchange number, the "call in" key having been restored, the connector H' is held up by the energization of relay 200 which has its circuit closed to the branch exchange battery by way of resistance 149 at the contacts of the "call out" key. Aside from this the connection to each subscriber is established precisely as in the case already described and when the conversation is finished the release of the connection is of course effected in the same manner.

Special clearing out circuits.

Although it is believed that the system will be fully understood from the foregoing description, it will be of advantage before closing to go over certain details which are more or less connected with the supervision, in order to avoid any chance of a misunderstanding. It will be clear from what has been said that the attendant operator at the branch exchange is charged with general supervision over all calls, both incoming and outgoing, and over the incoming calls in particular. Whenever a trunk line is in use the busy lamp associated therewith is lighted so that the operator knows at all times how many connections are up or in process of being established. When a through call is initiated, however, and is being set up in the first instance, the supervisory lamp associated with the trunk line in use is not lighted, and the call may go through and be answered without giving the attendant operator any signal: and this is as it should be, for she only needs the supervisory signal when she herself actually takes part in setting up the connection. It is noted in this connection that the attendant operator is given a disconnect signal when the called party hangs up his receiver. To proceed, in pursuance of her supervisory duties the attendant may from time to time listen in on the busy trunk lines to see how the

calls are progressing and especially if she notices a busy lamp which has been lighted a relatively long time and has received no disconnect signal on that trunk line. If the attendant should go in on a line prematurely before the connector has been operated her head set is connected across the line (note that there is a condenser in series with her receiver) and she can tell what is going on by talking to the distant toll operator, or if the number is being called she will hear the impulses. The operation of the connector is not interfered with because relay 200 is not connected in bridge of the line by operation of the listening key, due to the fact that relays 206 and 209 have not yet been energized. If the called party has answered the attendant will of course hear the conversation when she listens in.

But if the connector has already been operated and the operator listens in before the called party has answered the results are somewhat different. The circuits being in ringing position, relays 209 and 206 of the connector will be in energized position, and when the operator throws her listening key relay 200 is locked across the trunk line in the manner which was pointed out hereinbefore. This stops the ringing and in general produces the same results as though the called man had answered. Relay 200, it is noted, is completely energized and lights the supervisory lamp. Now if the calling party in the main exchange is a local subscriber no particular harm has been done. The attendant can assist the calling party to secure the desired connection in the branch exchange; or if the latter so desires, as when he gets all the information he wants from the attendant, he can hang up his receiver and release the connection, for the line relay of the second selector F' is at all times under his control. But if the calling party at the main exchange is a toll operator relay 24 at the repeater E' will have been energized and the connection will be locked up by the bridging of relay 200 across the line. This will be understood when it is recalled that relay 200 is energized in series with the battery feed relay 16 at the repeater E', the latter relay being effective, on toll connections, to close the circuit of relay 24 which in turn closes a local circuit for the line relay of the second selector F'. It will be evident therefore that relay 200 must be disconnected from across the line before the toll operator can release. If the called man should answer after all, relays 202 and 201 will be energized, relay 200 would be disconnected by the latter relay, and the attendant operator could leave the line without leaving it tied up. Or if the attendant operator should call the number over again or try another number for the toll operator the relay 200 would be disconnected by

the operation of the "call in" key. But if neither of the above operations takes place and the attendant simply restores her listening key the connection will be left in a permanent answered condition and the toll operator will be unable to release the switches. This condition is of course always evident to the attendant operator because her supervisory lamp is lighted.

- 10 From the foregoing consideration it will be apparent that when the attendant answers or listens in on a toll call and gets a permanent supervisory signal under the conditions named, she must perform some act which is 15 equivalent to a hanging up operation by a calling subscriber, in order to clear the line and put out her supervisory signal, and also, incidentally, to give the distant toll operator a disconnect signal. The required 20 clearing out operation is accomplished by momentarily operating the release key. By the operation of this key the line conductors of the trunk are opened and conductors 159 and 157 are grounded. When the trunk line 25 is opened relay 200 at the connector H' will no longer get battery from the repeater E' and will deenergize. It follows that the slow acting release relay 204 is deenergized also and the connector is restored to normal. 30 The grounding of the conductors 159 and 157 brings about a series of relay operations at the connector H', as described hereinbefore, resulting in the energization of relays 206, 35 209, 210 and 213. When the release key is restored relay 200 is partially energized by current flow from the lower line conductor to ground, as will be well understood by this time, relay 204 is energized, and the remaining relays of the connector which were energized by the operation of the release key are 40 locked up by the grounding of conductor 164. The results accomplished by the operation of the release key may now be summed up briefly as follows: Relay 200 has been un- 45 locked and disconnected from in bridge of the trunk line and the connector H' has been restored to normal. As a result of the former operation the supervisory signal at the attendant operator's position has been 50 cleared out, and furthermore, since the battery feed relay 16 at the repeater E' is deenergized immediately upon the opening of the line conductors at the release key, the relay 24 at the repeater E' is also deenergized, 55 the connection is again placed under the control of the distant toll operator, and the said toll operator is given a disconnect signal. Although the connector H' has been restored to normal, still, due to the locking 60 up of the various relays including in particular relay 206, the line relay 205 of the connector has been disconnected and the disconnect signal at the distant toll operator's position will therefore be permanent 65 and the connection will be left permanently

under her control, because there is nothing in bridge of the trunk line, and the battery feed relay 16 at the repeater E' necessarily remains deenergized. This would not be the case if the connector H' had simply been restored to normal position for then the line relay 205 would be in bridge of the trunk line and would energize in series with the battery feed relay 16 causing the connection to be again locked up. It will be seen that this is prevented by the circuit arrangement in which the release key grounds conductors 159 and 157, whereby the various relays in the connector are locked up as explained and the connector is placed, so far as its essential circuits are concerned, in the condition of having been operated to establish a connection. The toll operator may now release the connection simply by withdrawing her cord circuit from the jack in use, thereby deenergizing the line relay of the second selector F'. As already explained, in the condition of the circuits as they now exist this line relay controls the entire connection and upon deenergizing all the apparatus is restored to normal.

Having described my invention what I consider to be new and desire to have protected by Letters Patent will be pointed out in the appended claims.

What I claim as my invention is:

1. In a telephone system, a toll service trunking system comprising toll first and second selectors, a local trunking system comprising local first and second selectors, combination regular and toll connectors accessible to the second selectors of both trunking systems, and a private branch exchange trunking system comprising selector repeaters and branch exchange connectors, the said selector repeaters being accessible to the first selectors of both the toll and local trunking systems.

2. In a telephone system, a toll service trunking system comprising toll first and second selectors, a local trunking system comprising local first and second selectors, combination regular and toll connectors accessible to the second selectors of both trunking systems, and a private branch exchange trunking system comprising combination regular and toll transmission repeaters accessible to the toll and local first selectors, selector repeaters associated with said transmission repeaters, and branch exchange connector switches.

3. In a telephone system, a toll service trunking system comprising toll first and second selectors, a local trunking system comprising local first and second selectors, combination regular and toll connectors accessible to the second selectors of both trunking systems, a private branch exchange trunking system comprising selector repeaters and branch exchange connectors, the

said selector repeaters being accessible to the first selectors of both the toll and local trunking systems, and a directory numbering scheme without distinction as to the number 5 of digits between main and branch exchange telephone numbers.

4. In a telephone system, a toll service trunking system comprising toll first and second selectors, a local trunking system comprising 10 local first and second selectors, combination regular and toll connectors accessible to the second selectors of both trunking systems, a private branch exchange trunking system comprising selector repeaters and 15 branch exchange connectors, the said selector repeaters being accessible to the first selectors of both the toll and local trunking systems, calling apparatus whereby toll operators can complete connections over said toll 20 and branch exchange trunking systems, and means for giving the toll operators uniform answering and disconnect supervision regardless of whether main or branch exchange lines are called.

25 5. In a telephone system, a toll service trunking system comprising toll first and second selectors and main exchange connectors, a branch exchange trunking system comprising second selector repeaters and 30 branch exchange connectors, the said selector repeaters being accessible to said toll first selectors, two conductor trunk lines connecting said selector repeaters and branch exchange connectors, calling apparatus whereby toll operators can complete connections 35 over said trunking systems, and means for giving the toll operators uniform answering and disconnect supervision regardless of whether main or branch exchange lines are called.

40 6. In a telephone system, a main exchange and a branch exchange, a trunk line comprising only two conductors connecting said exchanges and terminating in a connector switch in the branch exchange, means including said trunk line and connector for connecting a calling line in the main exchange with a called line in the branch exchange, and means for supplying signaling current and talking current to the connected 45 called line exclusively from the main exchange over said trunk line.

55 7. In a telephone system, a main exchange and a branch exchange, a trunk line connecting said exchanges and terminating in a connector switch in the branch exchange, means including said trunk line and connector for connecting a calling line in the main exchange with a called line in the branch exchange, the said connector being controlled 60 in its connecting operation by interruptions produced in a circuit including the two sides of said trunk line in series, and means for supplying talking current to the connected 65 called line from the main exchange.

8. In a telephone system, a main exchange and a branch exchange, a trunk line comprising only two conductors connecting said exchanges and terminating in a connector switch in the branch exchange, means including 70 said trunk line and connector for connecting a calling line in the main exchange with a called line in the branch exchange, means for signalling the called station and for supplying talking battery thereto from 75 the main exchange, and means for disconnecting all bridges from the line at the branch exchange during conversation.

9. In a telephone system, a main exchange and a branch exchange, a trunk line comprising only two conductors connecting said exchanges and terminating in a connector switch in the branch exchange, means including 80 said trunk line and connector for connecting a calling line in the main exchange with a called line in the branch exchange, the said trunk line being extended directly through the said connector to the called line, means for cutting off all bridges from the line at the branch exchange, and means for 85 supplying talking current to the called line from the main exchange.

10. In a telephone system, means for connecting a calling and a called line, there being a special switching mechanism, a selector 90 repeater, and a final connector included in every established connection in the order named, means for supplying talking battery to the calling line through the windings of a line relay in said selector repeater, and 95 means for supplying talking current to the called line through the windings of a relay in said switching mechanism.

11. In a telephone system, means including a plurality of serially related automatic 100 switching mechanisms for connecting a calling and a called line, battery supply relay bridges in two of said switching mechanisms, circuit connections for supplying talking current to the calling line from the relay in the particular one of said two switching mechanisms whose position in the series 105 of switching mechanisms is nearest the called line, and circuit connections for supplying talking current to the called line from the 110 relay in the other of said two switching mechanisms.

12. In a telephone system, main and branch exchanges, an interexchange trunk line terminating in an automatic switch in 115 the branch exchange, means for operating said switch by interrupted current supplied from the branch exchange over a circuit including the two sides of said trunk line in series, and means for holding said switch in 120 operated position by current supplied from the main exchange.

13. In a telephone system, main and branch exchanges, an interexchange trunk line terminating in an automatic switch in 125

the branch exchange, a battery in each exchange, means for operating said switch by current from the branch exchange battery to connect with a called subscriber's line, means for connecting the main exchange battery to the trunk and for disconnecting the other battery from the trunk, and means for maintaining said switch in operated position controlled by current from the main exchange battery.

14. In a telephone system, main and branch exchanges, an interexchange trunk line terminating in an automatic switch in the branch exchange, a battery in each exchange, means for operating said switch over the two talking conductors of said trunk in series by current from the branch exchange battery, means for maintaining said switch in operated position by current flow over the two talking conductors of said trunk in series from the main exchange battery, and means for disconnecting said main exchange battery to release said switch.

15. In a telephone system, main and branch exchanges, an interexchange trunk line terminating in an automatic switch in the branch exchange, a relay and a source of current in bridge of the trunk line at said switch, means for closing and opening the conductors of said trunk line at the main exchange to control said relay to operate said switch, means for connecting a second current source in bridge of said trunk line at the main exchange after said switch has been operated, means for disconnecting said first relay and current source, and means in said switch responsive to current from said second source to prevent said switch from releasing.

16. In a telephone system, main and branch exchanges, an interexchange trunk line terminating in an automatic switch in the branch exchange, a relay and a source of current in bridge of the trunk line at said switch, means for closing and opening the conductors of said trunk line at the main exchange to control said relay to operate said switch, means operated automatically when the operation of said switch is completed for connecting a second current source in bridge of said trunk line at the main exchange, means for disconnecting said first current source, and means controlled over a conductor of said trunk line by current from said second source for preventing said switch from releasing.

17. In a telephone system, a trunk line extending to an automatic switch, means for controlling the operation of said switch over the two conductors of said trunk line in series, and means for controlling the release of said switch over a direct current circuit including one conductor of said trunk line and ground return.

18. In a telephone system, means includ-

ing a trunk line and an automatic switch for connecting a calling and a called line, means for controlling the operation of said switch by interruptions in a circuit including the two conductors of said trunk line in series to establish the connection, and a ground return circuit including only one conductor of said trunk line for controlling the release of said switch.

19. In a telephone system, means for connecting a calling and a called line comprising an automatic connector switch, a relay in bridge of the line at said switch for controlling the operation thereof, a second relay for preventing the release of said switch, means for automatically connecting said second relay in series with one line conductor after the connection is established, and means for disconnecting said first relay.

20. In a telephone system, means for connecting a calling and a called line comprising an automatic connector switch, a line relay in bridge of the line at said switch for controlling the same and for controlling the release thereof while operating, a second relay connected from one side of the line to ground at said switch for controlling the release thereof before the called party answers, and a third relay connected in series with one line conductor at said connector for controlling the release thereof during conversation.

21. In a telephone system, means including an automatic connector switch for connecting a calling and a called line, metallic talking circuit conductors extending continuously through said connector after the connection is established, a battery connected in bridge of said conductors between the said connector and the calling line, and a relay responsive to current from said battery connected from one of said talking conductors to ground at said connector to control the release thereof.

22. In a telephone system, means including an automatic connector switch for connecting a calling and a called line, metallic talking circuit conductors extending continuously through said connector after the connection is established, a battery connected in bridge of said conductors between the said connector and the calling line, a relay in said connector connected from one side of the line to ground before the called party answers for controlling the release of said connector, and a second relay connected in series with one line conductor at said connector for controlling the release thereof during conversation.

23. In a telephone system, a trunk line comprising two inductively connected sections, means for connecting a calling line with the first section of said trunk line, means including a selector and a connector for extending the second section of said

trunk line into connection with a called line, a line relay in said selector controlled over the said first section for operating said selector, a line relay at said connector in bridge of the second section after the selector has operated, a pair of contacts included in a conductor of the said second section and controlled by the line relay of said selector, means for disconnecting said selector line relay from said first section after the connection with the called line is established, and a local circuit for maintaining said selector line relay energized.

24. In a telephone system, means for connecting a calling and called line comprising in serial relation a repeating coil, a selector switch, and a connector switch, a controlling line relay for said selector connected in series with the windings on the incoming side of said coil, a controlling line relay for said connector connected in series with the windings on the outgoing side of said coil, and a pair of contacts on the selector line relay which are in series with one of the conductors extending from the said coil to the said connector line relay.

25. In a telephone system, a special switching mechanism, an incoming trunk line extending through said mechanism to the line relay of a selector switch, an outgoing trunk line inductively connected with said first trunk line at the said mechanism and extending to the movable wipers of said switch, means for operating said switch under control of its line relay to extend the second trunk line to the line relay of an idle connector switch, and means for interrupting one of the conductors of said second trunk thereafter by said selector line relay to operate said connector to connect with a called line.

26. In a telephone system, a calling and a called line, automatic switches for establishing a connection between said lines comprising two inductively connected sections, controlling relays in bridge of each section, means for reversing the direction of current flow in one section when the connection to the called line is completed, and means for reversing the direction of current flow in the other section when the called subscriber answers.

27. In a telephone system, a calling and a called line, automatic switches for establishing a connection between said lines comprising two inductively connected sections, means for reversing the direction of current flow in the last section when the connection to the called line is completed, and means for ringing the called subscriber controlled by said current reversal.

28. In a telephone system, a calling and a called line, automatic switches for establishing a connection between said lines comprising two inductively connected sections,

means for reversing the direction of current flow in the last section when the connection to the called line is completed, means for ringing the called subscriber controlled by said current reversal, and means for reversing the direction of current flow in the first section when the called subscriber answers.

29. In a telephone system, means including an automatic connector switch and a trunk line terminating therein for connecting a calling line and a called line, a controlling line relay in said connector in bridge of the line conductors of said trunk line, and means for automatically reversing the said line conductors when the connection to the called line is completed and before the called party has answered.

30. In a telephone system, means including an automatic connector switch and a trunk line terminating therein for connecting a calling line and a called line, a controlling line relay in said connector in bridge of the line conductors of said trunk line, means for automatically reversing the said line conductors when the connection to the called line is completed, and means for automatically disconnecting said line relay after the said lines have been reversed.

31. In a telephone system, means including an automatic connector switch and a trunk line terminating therein for connecting a calling line and a called line, a controlling line relay in said connector in bridge of the line conductors of said trunk line, means for automatically reversing the said line conductors when the connection to the called line is completed, and means for automatically disconnecting the said line relay after a definite interval whenever the said lines are reversed.

32. In a telephone system, means including an automatic connector switch and a trunk line terminating therein for connecting a calling line and a called line, a controlling line relay in said connector in bridge of the line conductor of said trunk line, means for automatically reversing the said line conductors when the connection to the called line is completed and means responsive to the reversal of said lines for automatically signalling the station on the called line.

33. In a telephone system, means including an automatic connector switch and a trunk line terminating therein for connecting a calling line and a called line, a controlling line relay in said connector in bridge of the line conductors of said trunk line, means for automatically reversing the said line conductors when the connection to the called line is completed, means for automatically disconnecting said line relay after the said lines have been reversed, and means responsive to the reversal of said lines for con-

necting a battery feed relay in readiness to supply talking current to the called line when the called party answers.

34. In a telephone system, means including an automatic connector switch and a trunk line terminating therein for connecting a calling line and a called line, a controlling line relay in said connector in bridge of the line conductors of said trunk line, means for automatically reversing the said line conductors when the connection to the called line is completed, means responsive to the reversal of said lines for automatically signalling the station on the called line, means for disconnecting said line relay during the signalling operation, and a second relay connected from one side of the signalling circuit to ground to prevent the release of said connector.
35. In a telephone system, means including an automatic connector switch and a trunk line terminating therein for connecting a calling and a called line, a switching through relay and a ring cut off relay in said connector for connecting the connector winners and controlling the ringing, respectively, means for energizing said relays at the proper times, and a reversing relay for reversing the line conductors of said trunk line whenever the said switching relay is energized.

36. In a telephone system, means including an automatic connector switch and a trunk line terminating therein for connecting a calling and called line, means in said connector for preventing the completion of the connection if the called line is busy, means for automatically completing the connection when the called line becomes idle, means for reversing the line conductors of said trunk line when the called line becomes idle and connection thereto is completed, and a ringing circuit completed automatically responsive to the reversal of said lines for signalling the called subscriber.

37. In a telephone system, an operator's position, means including an automatic connector switch and a trunk line terminating therein for extending a connection from said position to a called subscriber's line, means in said connector for preventing the completion of the connection if the called line is busy, means for automatically completing the connections when the called line becomes idle, means for reversing the line conductors of said trunk line when the called line becomes idle and the connection thereto is completed, means for giving the operator a signal while the busy condition exists, and a second signal controlled by the reversal of said lines to advise the operator that the busy condition has terminated.

38. In a telephone system, an operator's position, means including an automatic con-

nector switch and a trunk line terminating therein for extending a connection from said position to a called subscriber's line, means in said connector for preventing the completion of the connection if the called line is busy, means for automatically completing the connections when the called line becomes idle, means for reversing the line conductors of said trunk line when the called line becomes idle and the connection thereto is completed, and a signal lamp at the operator's position lighted in response to the reversal of said lines.

39. In a telephone system, an operator's position, means including an automatic connector switch and a trunk line terminating therein for extending a connection from said position to a called subscriber's line, means in said connector for preventing the completion of the connection if the called line is busy, means for automatically completing the connections when the called line becomes idle, means for reversing the line conductors of said trunk line when the called line becomes idle and the connection thereto is completed, a signal lamp at the operator's position lighted in response to the reversal of said lines, and means for extinguishing said lamp when the called party answers.

40. In a telephone system, a trunk line extending through an operator's position and terminating in an automatic connector switch, means for operating said connector over said trunk line to connect with a called line, a series of relays in said connector which are energized whenever the connector is operated to establish ringing and talking circuits, and special circuit connections whereby the operator can cause said relays to be energized while the said connector is otherwise in normal position.

41. In a telephone system, a trunk line extending through an operator's position and terminating in an automatic connector switch, means for operating said connector over said trunk line to connect with a called line, relays in said connector for changing its circuits from operating to ringing condition, and special circuit connections whereby the operator can energize said relays without operating the connecting mechanism of said connector.

42. In a telephone system, a trunk line extending through an operator's position and terminating in an automatic connector switch, a line relay in said connector normally in bridge of said trunk line, and special circuit connections whereby the operator can disconnect said line relay at will.

43. In a telephone system, a trunk line, means for extending the two opposite ends of said trunk line into connection with two subscribers' lines, respectively, two final connectors for completing the connections to

said lines, and means for supplying talking current to both lines from one of said connectors exclusively.

44. In a telephone system, a trunk line extending in two directions from an operator's position, means including automatic connector switches whereby each end of said trunk line may be extended into connection with a called subscriber's line, and means for supplying both of the connected subscribers' lines with talking battery from one of said connectors exclusively.

45. In a telephone system, a trunk line extending through an operator's position and terminating in an automatic switch, means including said trunk line and switch whereby a calling subscriber can extend connections to a called line, means for transmitting ringing current over said trunk line to signal the called subscriber when the connection is established, means whereby the operator can prohibit calls over said trunk line at her option, and a ring down signalling relay connected in bridge of said trunk line at the operator's position whenever a prohibited call is attempted.

46. In a telephone system, an automatic switch for connecting a calling and a called line, a relay in said switch for controlling the release thereof during operation, a second relay in said switch for controlling the release after the connection is completed and before the called party answers, and a third relay for controlling the release during conversation.

47. In a telephone system, an automatic switch for connecting a calling and a called line, three relays in said switch, a release magnet for said switch under control of the first relay while said switch is operating, means for shifting the control of said magnet to the second relay when the connection is completed, and means for shifting the control of said magnet to the third relay when the called party answers.

48. In a telephone system, means including a trunk line terminating in an automatic switch for connecting a calling and a called line, a line relay bridged across the trunk line for controlling the operation and release of said switch, means for disconnecting said relay after the switch has operated, and two other relays for preventing the release of said switch before and after the called party has answered, respectively.

49. In a telephone system, means including a trunk line and an automatic switch individual thereto for connecting a calling and a called line, a relay in said switch energized over one conductor of said trunk line and ground for preventing the release of said switch after the called line is connected with, and a second relay in said switch energized over the two sides of the called line in series for preventing the re-

lease of said switch after the called party has answered.

50. In a telephone system, an automatic switch, a trunk line terminating therein, means for operating said switch to connect a calling and a called line over said trunk line, a battery for supplying current for controlling the operation of said switch, a second battery, and means for connecting said batteries in series with the two line conductors of said trunk for supplying current to prevent the release of said switch.

51. In a telephone system, a main exchange and a branch exchange, a trunk line connecting said exchanges and terminating in a connector switch in the branch exchange, means including said trunk line and connector for connecting a calling line in the main exchange with a called line in the branch exchange, a battery in each exchange, means for supplying current to control the operation of said switch from the branch exchange battery, means for reoperating said switch to transfer the call to another called line, and means for connecting both batteries in series to supply current for preventing the release of said switch in case the second called line is busy.

52. In an automatic telephone system, a series of automatic switches, means rendering said switches available for common use by operators or calling subscribers for completing connections to called lines, and circuit arrangements whereby the release of said switches in an answered connection is controlled by the called party in case the calling party is an operator whereas if the calling party is a subscriber he retains control of the release throughout the connection independent of the called party.

53. In a telephone system, a trunk line, means rendering said trunk line available for use either by operators or calling subscribers in connecting with called lines, an alternating current relay and means controlled thereby for ringing called subscribers, and means for connecting said relay in bridge of said trunk only when the same is in use by an operator.

54. In a telephone system, a trunk line and an automatic switch controllable thereover, means rendering said trunk line and switch available for common use by operators or calling subscribers in connecting with called lines, a line relay for said switch connected in bridge of said trunk line during the establishment of a connection, and means for disconnecting said relay when the called party answers only in case the calling party is an operator.

55. In a telephone system, a trunk line and an automatic switch controllable thereover, means rendering said trunk line and switch available for common use by operators or calling subscribers in connecting with

called lines, a line relay for said switch connected in bridge of said trunk line during the establishment of a connection, means for retaining said relay in bridge of the trunk line to supply talking current to the calling line during conversation in case the calling party is a subscriber, and means for disconnecting said relay when the called party answers in case the calling party is an operator.

56. In a telephone system, a trunk line and an automatic switch controllable thereover, means rendering said trunk line and switch available for common use by operators or calling subscribers in connecting with called lines, a line relay for said switch connected in bridge of said trunk line during the establishment of a connection, means for reversing the connections of the relay to 15 said trunk when the called party answers in case the calling party is a subscriber, and means for disconnecting said line relay from the trunk when the called party answers in case the calling party is an operator.

57. In a telephone system, a trunk line and an automatic switch, means rendering said trunk line and switch available for common use by operators or calling subscribers in connecting with called lines, a 20 ring cut off relay, means for maintaining said relay energized during the operation of said switch, means for automatically deenergizing said relay to start the ringing operation when the called line is connected 25 with in case the calling party is a subscriber, and means for preventing the automatic deenergization of said relay in case the calling party is an operator.

58. In a telephone system, a trunk line and 30 an automatic switch, means rendering said trunk line and switch available for common use by operators or calling subscribers in connecting with called lines, a ring cut off relay, means for maintaining said relay energized during the operation of said switch, means for automatically deenergizing said 35 relay to start the ringing operation when the called line is connected with in case the calling party is a subscriber, means for preventing the automatic deenergization of said relay in case the calling party is an operator, and means whereby the operator can deenergize said relay at will.

59. In a telephone system, a trunk line and 40 an automatic switch for use by a calling subscriber in connecting with a called line, a ring cut off relay adapted when deenergized to apply ringing current to the trunk, means for maintaining said relay energized 45 during the establishment of the connection, and means for automatically deenergizing said relay responsive to the completion of the connection.

60. In a telephone system, a trunk line and 45 an automatic switch for use by a calling

subscriber in connecting with a called line, a ring cut off relay adapted when deenergized to apply ringing current to the trunk means for maintaining said relay energized during the establishment of the connection, 70 means for automatically deenergizing said relay responsive to the completion of the connection, means for energizing said relay when the called party answers, and a locking circuit for preventing further deenergizations of said relay during the same connection.

61. In a telephone system, an operator's switchboard, a trunk line extending through said switchboard and terminating in an automatic switch, means whereby said switch may be controlled either by the calling subscriber or by the operator at said switchboard to connect a calling and a called line, and means for giving the operator answering supervision only in case she controls said switch herself.

62. In a telephone system, an operator's switchboard, a trunk line extending through said switchboard and terminating in an automatic switch, means whereby said switch may be controlled either by the calling subscriber or by the operator at said switchboard to connect a calling and a called line, 80 means for giving the operator answering supervision only in case she controls said switch herself, and means for always giving the operator disconnect supervision when the called party hangs up.

63. In a telephone system, main and branch exchanges, a manual switchboard at the branch exchange, a trunk line connecting said exchanges, an automatic connector switch in which said trunk line terminates for use in establishing a main to branch exchange connection, and adapted to be controlled either by the calling main exchange subscriber or by the operator at said switchboard, a source of ringing current at each exchange, means for automatically ringing the called subscriber, and circuit arrangements whereby ringing current is supplied from the branch exchange in case said connector is controlled by the operator and from the main exchange in case the connector is controlled by the calling subscriber.

64. In a telephone system, means including a trunk line and an automatic switch for connecting a calling and a called line, a double wound line relay in said switch connected in bridge of said trunk line in series with the exchange battery, means operated when the called party answers for transposing the two wires by which said relay is connected to the trunk, and means for simultaneously short circuiting one winding of said relay.

65. In a telephone system, means including a trunk line and an automatic switch for connecting a calling and a called line, a bat-

- terry feed relay for the calling line connected in bridge of said trunk, means for reversing the connections of said relay when the called party answers to reverse the direction of current flow in the calling line, and means for shunting one winding of said relay to increase the supply of current to the calling line.
66. In a telephone system, a plurality of serially related automatic switching mechanisms for connecting a calling and a called line, inductive windings in two of said mechanisms, circuit connections for supplying talking current to the calling line from the winding nearest in the particular one of said two switching mechanisms whose position in the series of switching mechanisms is the called line, and circuit connections for supplying talking current to the called line from the winding in the other of said two switching mechanisms.
67. In a telephone system, a trunk terminating in a selector, a second trunk terminating in a connector, means for operating the selector to unite said trunks, a bridge across the talking conductors of the connector trunk including a line relay and battery connections for supplying current, a bridge across the selector trunk for energizing said line relay, means for interrupting the line relay circuit to operate the connector to connect with a called line, means responsive to the completion of the connection for opening said first bridge, and means for introducing a source of current in said second bridge to supply talking current to the called line.
68. In a telephone system, a trunk terminating in a selector, a second trunk terminating in a connector, means for operating the selector to unite said trunks, a bridge across the talking conductors of the connector trunk including a line relay and battery connections for supplying current, a bridge across the selector trunk for energizing said line relay, means for interrupting the line relay circuit in accordance with the last two digits in a called number to operate said connector to connect with a called line, means operated automatically at the end of the final digit for opening said first bridge, and means operated at substantially the same time for introducing a source of current in the second bridge to supply talking current to the called line.
69. In a telephone system, a selector and a connector, a temporarily established trunk connection extending through said selector and terminating in said connector, two talking conductors included in said trunk connection, a bridge of said conductors at said connector including a controlling line relay and a source of current, a second bridge at the other end of said conductors for energizing said line relay, means for interrupting the circuit to cause said line relay to operate the connector to extend the connection to a called line, means for introducing a source of current in the said second bridge to supply talking current to the called line, and means for opening the said first bridge so that the said talking current is supplied exclusively from said second bridge.
70. In a telephone system, a connector switch, a temporarily established talking circuit extending from a calling line to said connector, inductive connections dividing said circuit into two sections, a selector included in the second section, means for controlling said connector over the two talking conductors of the second section in series to connect with a called line, a bridge at said connector for supplying current to said second section while the connector is being operated, means for opening said bridge when the called line is connected with, and means at the junction of said sections for supplying current to said second section to provide talking current to the called station when the called party answers.
71. In a telephone system, a train of switches including a selector and a final connector for connecting a calling and called line, a common talking and operating circuit extending through said switches, a bridge at said connector for supplying current to said circuit while the connector is being operated, means for supplying current to said circuit for talking at a point ahead of said selector, and means for maintaining said bridge open during conversation.
72. In a telephone system, a train of switches including a selector and a final connector for connecting a calling and called line, a common talking and operating circuit extending through said switches, a bridge at said connector for supplying current to said circuit while the connector is being operated, means for supplying current to said circuit after the connector is operated at a point ahead of said selector, the current supplied from said point energizing the transmitter at the connected called line, and means for opening said bridge after the second current supply circuit is established and before the called party answers.
73. In a telephone system, means including a selector repeater and a final connector for extending a connection to a called line, a trunk extending between said switches including two talking conductors, a circuit for controlling the operation of said connector including the wipers of said selector repeater and said talking conductors in series, a circuit for supplying talking current to the connected called line also including said wipers and talking conductors in series, means associated with said connector for supplying

current to said first circuit, and means associated with said selector repeater for supplying current to said second circuit.

74. In a telephone system, means including a selector repeater and a final connector for extending a connection to a called line, a trunk extending between said switches including two talking conductors, a circuit for controlling the operation of said connector including the wipers of said selector repeater and said talking conductors in series, a circuit for supplying talking current to the connected called line also including said wipers and talking conductors in series, means associated with said connector for supplying current to said first circuit, means associated with said selector repeater for supplying current to said second circuit, and means responsive to the completion of the operation of said connector for shifting the point of current supply as set forth.

75. In a telephone system, a temporarily established trunk connection including two talking conductors, two bridges across said conductors at one end thereof, the first being open and the second closed, a relay in the second bridge and a source of current in the first bridge, a closed bridge at the distant end of said conductors including a relay and a source of current, said second relay being energized over a circuit including said two conductors and the second bridge in series, means associated with said second bridge for altering the circuit of said second relay to intermittently operate the same, a connector switch controlled by said second relay to extend said talking conductors to a called line, means associated with the said connector for again altering said circuit when the connector completes its operation, said first relay being responsive to such circuit alteration, and means controlled by said first relay for opening said second bridge and closing said first bridge.

76. A compound main and branch exchange trunking system for use by toll operators and local subscribers comprising toll first selectors, toll second selectors accessible only to said toll first selectors, local first selectors, local second selectors accessible only to said local first selectors, selector repeaters accessible to both toll and local first selectors, combination connectors accessible to said toll second selectors and to said local second selectors but not to said selector repeaters, and branch exchange connectors accessible only to said selector repeaters.

77. In a telephone system, a trunk line, an automatic switch, means for setting up a connection from a calling to a called line, including said trunk line and said switch in serial relation, a calling bridge in said trunk line used during the establishment of the connection to control said switch, a talking bridge in said trunk line used during con-

versation to supply talking current to the called line through said switch, a change-over means in said trunk line, and means in said switch for operating said change-over means to disconnect said calling bridge and 70 to connect up said talking bridge.

78. In a telephone system, a trunk line, automatic switching mechanism controlled over said trunk line to set up a connection from a calling line to a called line, a switch control bridge in said trunk line used during the setting up of said connection to control said switching mechanism, a battery supply bridge in said trunk line used to supply talking current to the called line, and means controlled from said switching mechanism for opening the first bridge and for closing the second.

79. In a telephone system, a trunk line, automatic switching mechanism controlled over said trunk line to set up a connection from a calling line to a called line, a control bridge in said trunk line for controlling said mechanism to set up the connection, a battery supply bridge in said trunk line used for supplying talking current to the called line, and automatically-operated means for substituting the second bridge for the first.

80. In a telephone system, a trunk line, automatic switching mechanism controlled over said trunk line to set up a connection from a calling line to a called line, a control bridge across the conductors of said trunk line for controlling said switching mechanism during the establishment of the connection, a second bridge, and means controlled by said switching mechanism for opening the first bridge and for substituting the second bridge before the called party answers.

81. In a telephone system, a trunk line, automatic switching mechanism controlled over said trunk line to set up a connection from a calling line to a called line, a control bridge across the conductors of said trunk line for controlling said switching mechanism during the establishment of the connection, a second bridge, and means operated automatically after the connection has been set up and before the called party answers to open the first bridge from across the trunk and to place the second bridge across the same.

82. In a telephone system, a trunk line, a line relay connected to said trunk line, automatic switching mechanism controlled by said line relay to set up a connection from a calling line to a called line, including said trunk line, a ringing-response relay, and means operated automatically upon the establishment of said connection for disconnecting said line relay and for substituting said ringing-response relay.

83. In a telephone system, a trunk line, automatic switching mechanism, means for

5 sending impulses over said trunk line to operate said mechanism to set up a connection to a called line, a relay responsive to ringing current received over the incoming end of said trunk line, and means responsive to the completion of said connection for connecting said relay to said trunk line.

84. In a telephone system, a trunk line, automatic switching mechanism, means for 10 sending impulses over said trunk line to operate said mechanism to set up a connection to a called line, a relay responsive to ringing current, means responsive to the completion of said connection for connecting said relay to said trunk line, and means controlled by 15 said relay when it is operated by ringing current for applying ringing current to the called line.

85. In a telephone system, a trunk line, 20 means controlled over said trunk line for setting up a telephone connection including said trunk line, a ringing response relay, and means automatically operated upon the completion of said connection for initially connecting said ringing response relay in operative relation to the trunk line over a circuit path independent of the extended portion of said connection.

86. In a telephone system, a trunk line, 30 automatic switching mechanism controlled over said trunk line to set up a telephone connection, a ringing response relay, and means automatically controlled for connecting said ringing response relay to said trunk line only after said automatic switching mechanism has been operated.

87. In a telephone system, a trunk line, a train of automatic switches for extending said trunk line to a called line, circuit arrangements in said trunk line normally in 40 condition for sending impulses to operate said switches, and means individual to said trunk line and controlled through one or more of said switches responsive to the completion of the connection for changing the said circuit arrangements from impulse sending to talking condition.

88. In a telephone system, a trunk line, a train of automatic switches for extending 50 said trunk line to a called line, circuit ar-

rangements in said trunk line normally in condition for sending impulses to operate said switches, a relay individual to said trunk line for changing the circuits thereof to adapt the same for conditions existing 55 during conversation rather than for sending impulses, and means for operating said relay responsive to the completion of the connection.

89. In a telephone system, a trunk line, a train of automatic switches for extending 60 said trunk line to a called line, circuit arrangements in said trunk line normally in condition for sending impulses to operate said switches, a relay individual to said 65 trunk line for changing the circuit thereof to adapt the same for conditions existing during conversation rather than for sending impulses, means for operating said relay responsive to the completion of the connection, 70 and means for preventing the said operation of said relay in case the called line is busy.

90. In a telephone system, a relay having 75 two windings, an external circuit for the first winding, a local circuit for the second winding, a resistance included in said local circuit, means for closing both circuits in such a manner that the effect of the current flow in one winding opposes the effect of the current flow in the other winding, means for 80 reversing the direction of current flow in the external circuit to operate the relay, and contacts on said relay for shunting said resistance.

91. In a telephone system, a relay having 85 two windings, an external circuit for the first winding, a local circuit for the second winding, a resistance included in said local circuit, means for closing both circuits in such a manner that the effect of the current 90 flow in one winding opposes the effect of the current flow in the other winding, means for reversing the direction of current flow in the external circuit to operate the relay, contacts on said relay for shunting said resistance, 95 and other contacts on said relay for opening said external circuit.

Signed by me at Chicago, Cook County, Illinois, this 10th day of June, 1920.

JOHN WICKS.
